MACHINE FOR PRESSING SOLES UPON
SHOES AND PAD THEREFORSidney J. Finn, Beverly, Mass., assignor to United
Shoe Machinery Corporation, Paterson, N. J.,
a corporation of New Jersey

Application April 3, 1929. Serial No. 352,278

125 Claims. (Cl. 12—33)

This invention relates to machines for pressing a shoe and a sole together to cause the sole to conform to the shoe bottom, the illustrated machine being especially adapted for use in the manufacture of shoes in which cement alone is relied upon to provide permanent attachment of the sole to the shoe.

In recent years, especially abroad, the interest of shoe manufacturers has been revived in the attachment of outsoles by the use of cement instead of sewed seams, nails, pegs, or the like. The attachment of outsoles to shoes by cement has long been known in this country as the "Compo" process. In the early use of this process 15 gutta percha cement was employed but more recently celluloid or pyroxylin cement has been found to be much better for the purpose than the cements earlier used. In order to secure firm and uniform adhesion of a sole to a shoe 20 by such cements, it is important that a high and substantially uniform pressure be applied to all parts of the sole where adhesion is desired, thereby forcing the sole against the shoe bottom, and that the pressure be maintained for a time long 25 enough to allow sufficient setting of the cement to avoid any possibility of the sole loosening at any point after the pressure is released. It is highly important that the shoe and sole be properly located with respect to each other before the 30 pressure is applied to the sole.

Heretofore in work of this kind the sole and shoe have been located relatively to each other on the sole pressing pad by the operator, who determined by his eye the position of the sole 35 with respect to the shoe and, by time-consuming hand manipulation made the necessary adjustments of the sole with respect to the shoe. Sometimes, in order to conserve the time of the operator of the sole pressing machine, the longitudinal position of the sole with respect to the shoe 40 was determined and a tack inserted through the heel-seat portion of the sole but even then the operator of the sole pressing machine had to determine the lateral position of the sole with 45 respect to the shoe. This procedure necessitates a separate operation and does not assure accurate positioning of the sole.

Heretofore the pad by which pressure was applied to the shoe sole consisted of an inflatable bag usually of rubber covered with leather to which compressed air was supplied to cause inflation of the bag and consequent pressure of the bag against the sole. This arrangement, however, requires the installation of a complicated

and expensive equipment to provide a supply of compressed air.

Important objects of this invention are to provide mechanism for quickly locating an unattached sole and a shoe to which the sole is to be cemented in proper relation to each other upon a sole pressing pad, to provide improved pressure-applying mechanism, and to provide self-contained mechanism for maintaining the pressure applied to the shoe and sole for the desired time after the shoe is removed from the pressure applying mechanism.

A feature of the present invention consists in improved means for engaging the edge face of a sole placed upon a sole pressing pad, said means 70 acting to hold the sole against movement in its own plane. In the illustrated machine the sole engaging members operate as feelers and are so constructed and arranged that they will engage a sole of any size in the position in which the sole 75 is placed by the operator upon the pad. That is, the operator may exercise his judgment as to the proper location of the sole with respect to the pad or may place it more or less at random on the pad, no special care or attention being required by the operator in placing the sole on the pad. The feelers will find the sole in any one of a number of different positions in which it is placed by the operator and will hold it in that 80 position. If the operator notices, after the sole 85 has been engaged by the feelers, that a different position of the sole on the pad is desirable, he may shift the sole and the feelers transversely of the pad without disturbing the holding relation 90 of the feelers upon the sole. Preferably and as illustrated, separate feelers are provided for the forepart of the sole and for the heel end of the sole. The forepart feelers comprise a pair of members for engaging the edge face of the sole at the sides of the toe, a pair of members for engaging the sole adjacent to the ends of the ball line, and a member for engaging the toe end of the sole. The toe end engaging feeler is locked against movement outwardly of the sole, while the members of each pair of the other forepart 95 feelers are locked against movement of separation relatively to each other. The heel holding means, as illustrated, comprises members which act as feelers similarly to engage opposite sides of the heel end of the sole. As illustrated, the forepart feelers are movable into and out of position over one end of the pad, their movement being preferably lengthwise of the pad, and the feelers for engaging the heel end of the sole are 100 movable into and out of position over the heel end 105 110

of the pad lengthwise thereof. Preferably and as illustrated, mechanism is provided for permitting the forepart feelers and the heel end feelers to move simultaneously into operative position on the pad and to withdraw them simultaneously from their position on the pad.

In the illustrated machine, in accordance with another feature of the invention, means for locating the shoe relatively to the sole is brought into position by operation of the sole holding feelers above referred to. Preferably shoe engaging members or gages are superimposed upon the feelers to locate the shoe relatively to the sole by engaging the shoe at points corresponding to the points at which the feelers engage the sole, and the shoe gages and feelers are arranged for relative adjustment to permit the proper extension of the sole beyond the shoe at those points where the sole extension is variable. Since the sole extension has its greatest variability adjacent to the ends of the ball line, means may be provided for relatively adjusting equally and oppositely the sole gages and feelers at the ends of the ball line to cause them to engage the shoe and sole at the corresponding points.

It may be desirable, after the sole has been engaged by the feelers, to orient the sole, that is, to change the direction of its longitudinal median line with respect to the pad. For this reason, and in accordance with still another feature of the invention, the pair of feelers which engages the sides of the toe portion of the sole and the pair of feelers which engages the sole adjacent to the ball line are arranged for movement transversely of the sole in either direction while they still hold the sole, that is, while each pair is held from relative movement of separation. Such movement of these members, however, is resisted by substantial friction. By applying pressure to either one of either pair of said feelers or to the shoe gages, that pair may be shifted transversely of the pad and hence the direction of the sole lengthwise of the pad may be shifted. The pair of heel end holding feelers is also arranged for movement transversely of the pad against frictional resistance while holding the sole, and the heel holding feelers may be shifted transversely of the pad while the forepart of the sole is held against movement by the forepart feelers slightly to distort a sole the swing of which does not correspond exactly to that of the shoe to which it is being attached, so that the sole will be located properly with respect to the shoe at the heel end thereof. In the illustrated machine means is provided for restoring each pair of feelers and shoe gages to central position, which means is operated automatically as an incident to withdrawal of the members from operative position on the pad.

As illustrated herein, and in accordance with other features of the invention, the sole engaging pad through which pressure is applied to the sole, comprises a dilatable or distortable member having sufficient exposed surface to receive the largest sole to be treated and having sufficient flexibility to enable it to conform to the shape of a shoe bottom when pressure is applied. Preferably and as illustrated, the dilatable member constitutes a portion of the wall of a closed vessel containing a fluid, preferably a liquid, and dilation of this portion is effected by deformation or distortion of another wall portion of the vessel, for example by pressure applied to its bottom portion by a plunger, the pressure being transferred by the liquid uniformly to the sole engaging wall of the

vessel and thence to the sole. In the illustrated machine such a vessel is confined in a light rigid box which encloses the vessel at substantially all portions except the portion of the top which is to engage the shoe soles. In manufacturing this apparatus, the vessel is preferably completely filled with water or other suitable liquid, air bubbles being eliminated, and then, by applying pressure to the exposed portion of the vessel, a predetermined quantity of the liquid is expelled and the opening hermetically sealed without the admission of air. Thus the vessel, though full of water, is not dilated and the area exposed for the reception of the sole is flabby and easily conformable to the sole and shoe presented to it.

Each of the pad boxes carries means for holding a shoe in pressing relation to the pad and of course a sufficient number of combined pad boxes and shoe supports will be provided to supply a machine and operator so that the shoes may be maintained under pressure long enough for the cement to set without delaying the operator.

In accordance with further features of the invention, the illustrated machine is provided with mechanism by which, after the shoe and sole have been properly located with respect to each other and to the pad, preliminary pressure may be manually applied to the shoe, and with means by which a portion of the vessel forming the pad may then be distorted to effect distortion of the portion of the vessel which engages the sole thereby to apply the required predetermined pressure to the liquid in the pad and hence to the shoe sole. Means is provided on the illustrated pad box for maintaining the vessel in distorted condition and hence making each pad box and shoe support a self-contained unit so that the pressure will be retained even if the arrangement is such that the shoe and the pad box are removed bodily from the machine. For obtaining the required predetermined final pressure, gravity-actuated means is preferably employed which, as illustrated, comprises a weight acting through compound leverage to distort the vessel. The weight, when allowed to act, applies, of course, a constant pressure to the means for distorting the vessel irrespective of the distance through which the weight may move.

When a small shoe is being operated upon, a larger area of the distortable or dilatable sole engaging member will be exposed at the ends of the shoe than when a large shoe is being operated upon. When the pressure is applied this exposed area at the ends of the shoe will bulge up thus rendering the heel seat portion and the toe portion of the sole unduly convex and also preventing the required pressure per unit of area from being applied to the bottom of the shoe by a predetermined amount of distortion of the bottom of the vessel. Hence, in the illustrated machine, and in accordance with still another feature of the invention, masking-off means are provided at the toe and heel ends of the pad. These means comprise separate stiff plates arranged at the toe and heel ends of the pad and adjustable lengthwise of the pad over the outer surface thereof, the inner ends of the plates being preferably curved to correspond approximately to the curvatures of the ends of a shoe sole. When a small shoe is being treated, these plates may be adjusted inwardly to prevent abnormal distension or dilation of the pad and to cause the pressure applied to the bottom of a small shoe to be substantially the same per square inch as that applied to a large shoe.

- The liquid containing vessel forming the pad is preferably integrally formed of rubber molded over a core and vulcanized. Preferably the top of the vessel or dilatable member has incorporated 5 therein a strengthening layer of fabric to control the stretching of this portion of the vessel without affecting its conformability to the shape of the shoe bottom. In order to control the upward deflection of the exposed surface of the vessel, metallic plates may be inserted in the rubber during the manufacture of the vessel at the forepart or at the heel part engaging portions of the vessel or at both. These plates are preferably of thin spring steel provided with perforations 10 through which rubber may extend and bond the plates into the structure of the vessel. In order to afford the desired higher flexibility of the forepart engaging portion of the vessel the steel plate, if one is used in that portion of the vessel, 15 may be slit or slotted, preferably in directions approximately perpendicular to the periphery of the sole.
- In the manufacture of many shoes, particularly women's shoes, it is important that pressure be 20 so applied to the sole that the forepart and heel part will remain relatively flat while the margins of the shank portion of the sole will be bent closely against the upper to form a close shank having a convex transverse curvature. I have found that 25 these results can best be secured by a pad the sole engaging face of which is shaped to correspond to the longitudinal shape and curvature of the bottom of an average shoe, the forepart and heel part engaging portions being relatively flat and 30 the shank engaging portion having a convex curvature both transversely and longitudinally of the sole. When the operator places a shoe sole upon the pad and presses lightly upon it, the flabby doubly curved shank portion of the pad is easily deflected, responds to the pressure of the sole, and 35 is caused to change its contour, the shank engaging portion of the pad then becoming concave transversely and the portions of the pad at each side of the shank assuming a convex contour 40 which, when pressure is applied, enables the pad to wrap the margins of the shank portion of the sole toward the shoe upper.
- These and other features of the invention, including various other novel combinations and arrangements of parts, will appear more fully from 45 the following detailed description when read in connection with the accompanying drawings and will be pointed out in the appended claims.
- In the drawings,
- Fig. 1 is a perspective view of a machine embodying the present invention;

- Fig. 19 is a plan view similar to the left-hand portion of Fig. 6 showing mechanism for adjusting the members which engage the edge face 100 of the forepart of the sole equally and oppositely with respect to the shoe engaging members; and
- Fig. 20 is a sectional view on the line XX—XX of Fig. 19.
- The illustrated machine for locating a sole 105 and shoe relatively to each other and for pressing the shoe and sole together while cement with which they are coated sets comprises a table 20 (Fig. 1) supported by upright angle bars or legs 22 to which, at their upper ends, end plates 24 110 are attached and, at their lower ends, angle bars 26 are secured to hold them in vertical alinement. On the table 20 is a pad box 28 which encloses a flexible, dilatable and distortable vessel 30 forming a sole pad, the portion of the upper surface 115 of a wall 31 of the vessel being exposed. This wall 31 is hereinafter referred to as a dilatable member or simply as a pad, and the bottom 33 of the vessel is referred to as a distortable member or portion. A cover 32 is attached at 34 to 120 the box and is provided with a sole-shaped opening of a size to receive the largest sole to be treated by the machine. The vessel 30 forming the pad preferably contains a liquid such as water by which it is filled but not distended so that its 125 exposed surface is flabby and readily conformable to a sole placed thereon. The longitudinal contour of the pad is such, however, that when an operator places a sole on the pad in a roughly selected position and presses down upon it lightly 130 the sole will assume a longitudinal contour substantially like that of the shoe bottom to which it is to be attached.
- The purpose of the mechanism about to be described is to find and grasp a sole thus placed on 135 the pad in a position selected by the operator, to hold the sole in the position in which he has placed it, and to locate a shoe placed upon the sole properly relatively thereto, provision being made also for shifting the shoe and sole, or either end thereof, relatively to the pad when necessary or desirable. At one end of the table 20 an upright plate 36 is adjustably secured to the end plates 24 by clamping gibs 38 and at the opposite end a similar plate 40 is similarly secured. To the plate 36 is pivoted at 42 a plate 44 which carries the mechanism for engaging the forepart of the sole and shoe, a similar plate 46 being similarly mounted on the plate 40 for carrying the mechanism for engaging the rear portion of the sole 140 145 150

and shoe. The plates 44 and 46 are held in adjusted position about their pivots 42 by braces 48 and 49 (Fig. 2) pivoted at their upper ends respectively to the plates 44 and 46, and adjustably held by bolt-and-slot connections 47 to the upright plates 36, 40. At each side of the plate 44 are two strips 50, 51 spaced apart by a narrow strip 52 to provide grooves between the strips 50, 51 in which the side edges of a slide 53 are guided. A similar slide 54 is similarly mounted on the plate 46 to carry the heel end engaging mechanism.

Referring now to Fig. 8 and confining the description to the mechanism for engaging the forepart of the sole and shoe, it will be seen in this exploded view that the slide 53 is provided with upstanding ears 56, to each of which is pivoted a block 58 by a screw 60. To the under side of the blocks 58 are secured a relocating plate 62 and a supporting plate 64. To the upper side of the blocks 58 are secured a plate 66 similar to 64 and a relocating plate 68 similar to 62. The blocks 58 space the outer ends of the plates 64, 66 apart, and between the plates near their inner ends two pairs of levers 70, 71 and 72, 73 are pivoted, the upper pair of levers being directly superposed upon the lower pair and having their inner arms (that is, those at the right of Fig. 8) longer than the corresponding arms of the lower pair 72, 73. Pivot pins 74, 75 pass through holes in the upper plate 66 and in the lower plate 64, the pin 74 serving as a common pivot for the levers 70, 72 and the pin 75 providing a common pivot for the levers 71, 73. Spacing collars or washers 78 are provided on the pins 74, 75 above and below the levers to provide space for a cam plate 80 below the levers and for a similar cam plate 82 above the levers. Each of the cam plates 80, 82 has three straight slots 84, 86, 88. The slots 84 and 86 of each plate are inclined with respect to each other, the inner ends being nearer together, while the slot 88 extends in a direction to bisect the angle formed by the other two slots. The slots 88 in the cam plates 80, 82 are engaged by a pin 90 held at its lower end in the plate 64 and at its upper end in the plate 66. The slots 84, 86 in the upper and lower cam plates 80, 82 are engaged, respectively, by a pin 92 projecting upwardly from the end of the outer arm of the lever 70 and by a similar pin projecting downwardly from the end of the outer arm of the lever 72. The levers 71, 73 at the opposite side of the mechanism are similarly connected, respectively, to the slot 86 in the cam plate 82 and to a similar slot in the lower cam plate 80. The inner end of each of the levers 70, 71 is provided with two work engaging members 95, 96, the members or gages 95 being adapted to engage the shoe in the region of the ball line and to overlie the sole, and the members or feelers 96 being adapted to engage the edge face of the sole. The inner end of each of the levers 72, 73 is provided with two work engaging members 97, 98, the members or gages 97 being adapted to engage the shoe in the region of the tip line and to overlie the sole, and the members or feelers 98 being adapted to engage the edge face of the sole. The members or feelers 96 are formed on arms 100 which are pivoted at 102 to the levers 70, 71. The members or feelers 98 are formed on arms 104 pivoted at 106 to the levers 72, 73. The members 95, 96 and 97, 98 may be adjusted relatively to each other. For this purpose a headed stud 108 (Fig. 9) is mounted for rotation in the end of each of the levers and has an eccentric portion

110 which engages a hole in the arm 100 or 104, the hole being elongated in the direction in which the levers extend. By turning the studs 108 by means of their square heads, the arms 100 and 104 may be swung inwardly or outwardly to locate the sole engaging members or feelers 96, 98 relatively to the shoe gages 95, 97 in accordance with the amount which the sole projects outwardly beyond the upper at the particular part of the shoe which the members engage. Since the sole projection at the sides of the shoe varies not only in different shoes but at opposite sides of the same shoe, depending on whether it is a right or a left shoe, the engaging members 96, 98 are made independently adjustable relatively to the members 95, 97. For convenience in making these adjustments the positions of the eccentric portions 110 of the studs 108 are indicated by pointers 112 secured to the heads of the studs.

To engage the end of the sole and shoe a bar 114 is provided which has at its inner end a shoe gage 116 and a feeler 118 for engaging the end of the sole. Since the projection of the sole at the end of the shoe is substantially constant, this feeler and gage are not made relatively adjustable. The bar 114 is mounted to slide lengthwise on the top of the plate 66, being guided therein by ribs 120 on the under side of a cap plate 122 which is held in place by screws 124 which engage threaded holes in the ends of the pivot pins 74, 75. Under the plate 122 and pivoted on upward projections of the pins 74, 75 are locking pawls 126, 128, each having a tooth 130 arranged to engage ratchet teeth 132 formed on opposite edges of the bar 114. The pawls are urged toward the bar 114 by springs 134 connected between pins located respectively on the pawls and on the cap plate 122. The teeth 132 on one side of the bar 114 are one half a tooth in advance of those on the other side of the bar, so that the pawls act differentially on the bar to prevent outward movement thereof, that is movement away from the shoe. The pawls 126, 128 are normally held out of engagement with the bar by pins 136 on the levers 70, 71 which engage inclined tails 138 on the pawls. The bar 114 is normally held toward the shoe by a light helical spring 140 (Fig. 7) connected between a pin 141 on the outer end of the bar 114 and a pin 142 on the cap plate 122. The cam plates 80, 82 are also urged toward the shoe by long, relatively strong, helical springs, the upper one 144 of which is connected to a pin 146 on the cam plate 82 at one end and at the other end passes through the spring 140 and is connected to the same pin 142. The lower spring 148 is similar and is similarly connected at one end to a pin 150 on the cam plate 80 and at the other end to a pin 152 depending from the supporting plate 64. The pins 146 and 150 pass respectively upwardly and downwardly through wide slots 154, 156 formed in the plates 66, 64, respectively, and when the cam plates are drawn outwardly against the springs 144, 148, the pins 146, 150 engage bell-mouthed notches 158, 159, respectively, in the relocating plates 62, 68, to centralize the work engaging members after use. The plate 64 has blocks 160 attached to its under side near its inner end on each of which is mounted a roll 162. These rolls normally rest on cam bars 164 attached to the strips 50. The slide 53 is moved toward the pad, when permitted to do so, by a weight 166 (Fig. 2) connected to the lower end of a chain 168 which passes over a pulley 170 on the pin 42 and has its upper

end attached at 172 to the slide 53 (Fig. 7), the plate 44 being slotted at 173 to permit such attachment of the chain. When the slide 53 is moved toward the pad by the weight 166, the 5 rolls 162 pass beyond the inner ends of the cam bars 164 and rest upon the strips 50. This permits the mechanism carried between the plates 64, 66 to drop downwardly about the pivots 60 so that the sole engaging members 96, 98, 118- 10 will rest upon the pad or dilatable member 31. Inward movement of the slide 53 is limited by engagement of the inner end of the slide with a stop 174 (Fig. 7) secured to the inner end of the plate 44, the sole engaging members being 15 then in position to grasp the forepart of the sole.

To withdraw the slide 53 from the pad, a rectangular link 180 (Fig. 8) is arranged between the cam plates 80, 82, and a pin 182 on the cam plate 80 extends upwardly into the link 180 for 20 about half the thickness of the link and a similar pin 183 on the cam plate 82 extends downwardly for half the thickness of the link. A pull outwardly on the link 180 therefore will retract the cam plates 80, 82 against the tension of the 25 springs 144, 148 until the pins 92 reach the ends of the slots 84, 86, and then the slide 53 will be withdrawn. The link 180 is connected to a chain 184 which passes over a pulley 186 (Fig. 2) mounted on the plate 44, thence through a slot 30 in the upright plate 36, and over a pulley 188 mounted on the legs 22 to a treadle lever 190 to which it is secured at 191. The treadle lever 190 is fulcrumed on a rod 192 supported by the legs 22 (Figs. 1 and 2). The treadle lever has 35 a brace 194 to which a spring 196 is connected to lift the lever. The free end of the lever is outturned and carries a treadle 198. On the treadle lever is pivoted a latch 200 which engages under the front angle bar 26 to hold the 40 treadle depressed and the latch 200 has a tail 202 overlying the treadle, by pressure on which it may be released.

The operation of the mechanism described for holding the forepart of the sole and locating the 45 forepart of the shoe relatively to the sole is as follows: The operator places a sole of any size within a wide range of sizes upon the dilatable member or pad 31 in any convenient position; that is, he does not need to exercise any special 50 care in locating the sole. Preferably he will press the shank portion of the sole against the shank portion of the pad, which portion, being then undilated, readily responds to the pressure of the sole, and the double convex contour of this portion of the pad is changed by pressure of the sole to a transversely concave contour where it is engaged by the sole and to a transversely convex contour at each side of the shank portion of the sole. While thus holding the sole with his 55 fingers, the operator, with his foot, releases the latch 200 and allows the treadle to rise. The weight 166 on the chain 168 causes the slide 53 to advance toward the pad until arrested by engagement with the stop 174, the cam bars 164 having meantime allowed the levers 70, 71, 72, 60 73 and the end abutment bar to drop so that the positioning members 96, 98, 118 rest upon the dilatable member 31. During this movement of the mechanism the feeler member 118 on the bar 114 has engaged the end of the sole and the bar has had its movement arrested thereby, the light spring 140 having been tensioned as the slide 53 continued to advance. When the movement of the slide was arrested by the slot 174, the pairs 65 of levers 70, 71 and 72, 73 were opened with their 70 sole engaging members or feelers 96, 98 resting on the surface of the dilatable member.

If one of the feelers 98 in its closing movement effected by inward movement of the cam plate 80 under the influence of the spring 148 engages the edge face of the sole earlier than the other, the plate 80 shifts sidewise about the pin 90 as a center until both feelers 98 engage the sole, whereupon the levers 72 and 73 and the feelers are held against separation. Meantime the 80 spring 144 has similarly operated the cam plate 82 to close the levers 70, 71 upon the sole, bringing the feelers 96, 98 against opposite edge faces of the sole in the region of the ball line and locking them against separation. As the levers 70, 71 approached their closed position, they released the pawls 126, 128, causing the bar 114 to be locked against movement away from the sole with its feeler 118 engaging the edge face of the end of the sole. Since the gage surfaces 116, 97 and 95 are in vertical planes disposed inwardly of the sole with respect to the planes of the feeler surfaces 118, 98 and 96, ledges 204 (Figs. 8 and 9) between these surfaces overlie the margin of the sole and hold it from upward movement. The feelers have thus found the forepart of the sole and now hold it at five points on its periphery. The sole may, however, if desired, be shifted bodily transversely of the pad or as to orientation, for, although the pairs of feelers 96, 98 are effectively held against relative movement of separation, each pair is independently movable against some frictional resistance in either direction transversely of the pad, the cam plates 80, 82 being of course swung about the 100 pin 90 in a direction opposite to that in which the corresponding pair of members 96 and 98 is moved. The size of the link 180 is such as to permit transverse movement of the pins 182, 183 therein if they move in opposite directions, and 110 if they move in the same direction the chain 184 and link 180 can swing with them.

While, under some conditions, the mechanism described will be effective for holding the sole, and the shoe may be located in proper relation 120 to the sole so held by simply placing the shoe upon the sole with its toe and sides in engagement with the gages 116, 97 and 95, it is desirable in order to meet all conditions to provide feelers for finding and holding also the rear portion of 125 the sole, particularly since it is sometimes necessary slightly to distort the sole, in order to make the sole fit the shoe bottom, by shifting the rear portion of the sole transversely relatively to the forepart. Accordingly, feelers for finding and 130 holding the rear portion of the sole, which feelers can be shifted transversely of the pad, and gaging means for locating the rear portion of a shoe in proper relation to the rear portion of the sole are provided, as illustrated in Figs. 1, 2, 135 3, 14, 15 and 16. On the slide 54, the mounting of which on the right-hand side of the machine has already been described, are ears 206 (Fig. 14) to which blocks 208 are pivoted by screws 210. Secured at their outer ends respectively to the lower and upper faces of the blocks 208 are plates 212, 214. Mounted between these plates are a cam plate 216 similar to the cam plate 80, two levers 218, 220 similar to the levers 72, 73, a sliding end abutment bar 222 similar to the bar 114, and two pawls 224, 226 similar to the pawls 126, 128. The cam plate 216 (Fig. 3) is urged inwardly by a spring 227 connected between a pin 229 and the lower side of the cam plate and a pin 231 on the plate 212. 140 145 150

The lever 218 and the pawl 224 have a common pivot (Fig. 14) on a stud 228 mounted in the lower and upper plates 212, 214, and the lever 220 and the pawl 226 are similarly pivoted on 5 the opposite side of the mechanism. Beneath the levers 218, 220 is a spacing member 230 to provide room for the cam plate 216 to operate. The outer ends of the levers 218, 220 are provided with downwardly projecting pins which engage 10 inclined slots 231 in the cam plate 216 which act, when the cam plate is allowed to be operated by its spring 227, to close the inner ends of the levers toward the sole. The cam plate 216 has in its inner end a slot 233 (Fig. 3) which 15 is engaged by a pin 235 projecting upwardly from the plate 212 about which the plate can shift to permit movement of the inner ends of the levers 218, 220 transversely of the pad 31. When the cam plate 216 is drawn outwardly to separate 20 the inner ends of the levers, the pin 229 projecting downwardly from the cam plate engages the bell-mouthed rear end of a slot 237 (Fig. 14) in the plate 212 which causes the cam plate to be relocated in central position. The bar 222 is 25 guided for longitudinal movement between ribs 232 formed on the spacing member 230 and is urged inwardly by a spring 234 (Fig. 3) connected at one end to a pin 236 on the plate 214 and at the other end to a pin 238 extending 30 through a slot in the plate 214 and secured to the bar 222. When the levers 218, 220 are in open position, pins 240 fixed in the levers hold the pawls 224, 226 out of engagement with teeth 242 formed on the edges of the bar 222. 35 The inner ends of the levers 218 and 220 are provided with gage members 250 and feeler members 252 which are relatively adjustable in the same manner as the members 97 and 98 by eccentric adjusting studs 253. The members 250 40 are adapted to engage the shoe and the members 252 to engage the sole. Lips or ledges 254 are provided on the feeler members 252 which extend over the sole to hold it against upward movement. The parts of the members 252 which 45 engage the edge of the sole are preferably curved in horizontal planes, as shown in Fig. 15, to provide substantially point contacts with the sole so that they will accurately position the rear parts of soles of different shapes. The inner 50 end of the bar 222 is turned downwardly at a right angle to provide an end abutment 256 for the rear end of the sole and shoe.

The plate 212 has rolls 258 mounted thereon which engage cam bars 260 which, when the 55 slide 54 is moved toward the pad, allow the members 252, 256 to descend into engagement with the exposed surface of the dilatable member 31. To move the slide 54 inwardly toward the pad, a weight 262 (Fig. 1) is provided which is 60 attached to a chain 264. The chain extends upwardly over a pulley 266 pivoted to the plate 40 at 42 through a slot 268 (Fig. 1) in the plate 46 and is attached to the slide 54. To separate the 65 positioning members 250 and 252 and to withdraw the slide 54, a chain 270 is connected to the cam plate 216 at 272 (Fig. 14), extends over a pulley 274 (Fig. 2) mounted on the plate 46, is carried over a pulley mounted similarly to the pulley 188 on the same axis, and is connected 70 at 191 to the treadle lever 190 so that depression of the treadle lever 190 will retract the positioning mechanism at the toe end of the pad and that at the heel end of the pad simultaneously. 75 During the operation of locating the forepart of the sole and the shoe, as above described, the slide

54 will move inwardly in response to the weight 580 262, causing the positioning members 252 and 256 to advance toward the shoe and drop into engagement with the dilatable member 31, due to passage of the rolls 258 off of the ends of the cam bars 260. The movement of the slide 54 is limited by engagement of the slide with a block 271 (Fig. 14) pivoted by a screw 273 on the plate 46. The screw is located at different distances from the side and end faces of the block so that, by rotating the block, any one of these faces may be utilized as a stop for the slide 54 and hence the position of the gages 250 and feelers 252 lengthwise of the pad may be varied to adapt them for engaging soles of different lengths. When tension 85 on the chain 270 is released, the cam plate 216 is moved inwardly by its spring 227, causing the feelers 252 to close upon and find the sole in position where it has been placed by the operator and the abutment 256 is locked against outward movement. It being understood that the forepart feelers and gages have operated as described simultaneously with the heel end feelers and gages, the shoe may now be placed on the sole and, assuming that proper relative adjustments of the shoe 90 and sole engaging members have been made, the shoe will be properly located relatively to the sole at all parts of its periphery. In placing the shoe between the gage members 250, it may be necessary to shift the rear part of the sole transversely 95 relatively to the forepart one way or the other in order for the sole properly to fit the shoe. For this purpose the levers 218, 220 may be moved together transversely of the pad, the cam plate 216 swinging in the opposite direction and the 100 levers 218, 220 being at the same time locked against separation by the cam plate. This movement is, of course, usually slight and is necessary only when the swing of a died out sole does not correspond accurately to the swing of the last. 105

The shoe and sole having been properly located with respect to each other in the manner and by the means described, it is desirable to apply preliminary pressure to the shoe and last to force the shoe down upon the dilatable member 31 to 110 cause the sole to be brought into contact with the shoe bottom substantially throughout its extent and to bring the sole and shoe bottom into proper vertical relation to the dilatable member in order that sufficient additional pressure may be applied 115 to the sole by distortion of the vessel 30, of which the dilatable member 31 is a part, without undue distortion of the exposed portion thereof.

For this purpose a bail or yoke, comprising arms 280 pivoted at their lower ends at 281 to 120 the box 28 and fixedly joined at their upper ends by a transverse bar 282, is provided. In the bar 282 is mounted a vertically movable plunger 284 having on its lower end a foot 285 to engage the top of the cone of the last. Prior to the introduction of a shoe, the yoke may be swung outwardly of the pad until one of the arms 280 engages the stop pin 286 (Fig. 1). For the toe portion of the shoe a toe rest 288 is provided which is mounted for vertical movement in a transverse 125 bar 292 secured to upright arms 294 pivoted at 296 to the box 28. The toe rest, as shown in Fig. 4, comprises a block 288 having a transversely concave lower face to which a covering 289 of suitable material, such as leather or felt, is secured by screws 291. The block 288 is rotatably attached to the lower end of a plunger 290 by a screw 293 and a pin 295 in the plunger engages a slot in the block 288 to limit the turning movement of the block, sufficient movement being per- 130 140 145 150 155

mitted to enable the concave shoe engaging face of the rest properly to engage the toe portions of right and left shoes. The forepart yoke, comprising the parts 292, 294, 294, which carries the toe rest, may be swung outwardly against a stop pin 298 but such movement of the forepart yoke is not essential since, when the yoke carrying the last supporting foot 285 is swung out of the way, the toe of the shoe may be readily introduced under the toe rest 288, the rest at that time being held in elevated position by a spring 300. A similar spring 302 is provided to hold the plunger 284 in raised position. A pawl 304 (Fig. 3) is mounted on each of the transverse bars 282, 292, to engage suitable teeth formed on the plungers 284, 290, the pawls being held in engagement with the teeth by springs 306 and being releasable by engagement of the operator's hands with upwardly extending portions 308 of the pawls.

To depress the plunger 284 the following mechanism is provided: A bracket 310 is pivoted at 312 to a projection 314 (Fig. 5) on the table 20. When not in use the bracket 310 swings by gravity to the right against a stop 316 on the table 20. When in use, the bracket is swung into a substantially vertical position against a ledge 318 on the projection 314. The bracket 310 is bored to receive a sleeve 320 (Fig. 3) and in the sleeve is a plunger 322 having a head 324 which, when the bracket is in vertical position, will be located over the top of the plunger 284 which engages the top of the last. The sleeve 320 and plunger 322 are held normally raised by a spring 326 (Fig. 1) which engages a pin 328. This pin extends through a long slot 329 in the bracket 310 through a short slot 330 in the sleeve 320 and is fixed in the plunger 322, as is clearly shown in Fig. 3. The upper end of the sleeve 320 is bifurcated and between the bifurcations is pivoted at 332 a lever 334 (Figs. 1 and 3) having a cammed surface 336 which engages the plunger 322 and operates, when the lever 334 is swung forwardly, to depress the plunger 322 relatively to the sleeve 320. A pawl 338 pivoted on the bracket 310 engages teeth on the sleeve to permit downward and prevent upward movement of the sleeve. The pawl may be released by pressure on an upwardly extending portion 340. On the bracket 310 is a projection 342 which, when the bracket is swung toward vertical position, will engage the rear arm 280 of the heel end yoke and swing it also into vertical position to locate the plunger 284 over the last if it has not already been so located.

For depressing the plunger 290 carrying the toe rest 288, a substantial duplicate of the mechanism described for the last depressing plunger 284 is provided, some of the parts being reversely arranged and of slightly different dimensions. Since the description given applies to either mechanism, each part of the toe rest depressing mechanism has been designated by the same reference numeral used to indicate the corresponding part of the mechanism described for depressing the rear end of the last. It is to be understood that both brackets 310 may be moved into vertical position, the sleeves 320 pushed down and the two levers 334 operated at the same time to depress both ends of the shoe simultaneously.

When the operator has placed a shoe on the pad as described and wishes to apply initial or preliminary pressure to the shoe and last to press it against the sole on the pad, he swings the brackets 310, 310 into vertical position, thus causing the plunger 284 and one of the plungers 322 to be brought into vertical alinement over the top of the last, as shown in Fig. 3, and the other plunger 322 and the plunger 290 to be brought into vertical alinement over the toe portion of the shoe. For this purpose the levers 334, 334 may be grasped, one in each hand of the operator, and swung into upright position, the cam surfaces 336, 336 being so formed that this movement of the levers does not cause depression of the plungers 322, 322. Whatever space there may be between the last and the plunger 284, between the shoe and the plunger 290, or between the upper ends of these plungers and the plungers 322, 322, or both, will be taken up by pushing downwardly on the levers 334, 334, flanges 335 being provided on the levers 334, 334 to prevent the operator's hand from slipping downwardly on the levers. The sleeves 320, 320 will thus be pushed downwardly to take up these spaces and insure that the plungers 284, 290 are brought into engagement with the last and shoe, and, if desired, some downward pressure may thus be applied to the shoe, this pressure being of course held by the pawls 304, 304. The levers 334, 334 are then swung over toward the operator into substantially horizontal positions, causing the cam surfaces 336 to depress the plungers 322, 322 and hence the plungers 284, 290 to apply preliminary pressure to the shoe and last. If, in the judgment of the operator, the preliminary pressure thus produced is insufficient, he may throw the levers 334, 334 into upright positions, push down the sleeves 320, 320, and again operate the levers 334, 334 to increase the preliminary pressure. The pawls 304, 304 will of course retain the pressure thus produced and the pressure may be built up to the desired extent. Under usual conditions, however, a single operation of each of the levers 334, 334 will be sufficient to produce the required preliminary pressure to locate the shoe vertically in proper relation to the body of the dilatable member 31.

The preliminary pressure thus applied being held by the pawls 304, 304, the levers 334, 334 may be thrown back, whereupon the springs 326, 326 will lift the plungers 322, 322 as far as permitted by the slots 330, 330, thus freeing the brackets 310, 310 carrying the preliminary pressure applying mechanism for outward swinging movement by gravity about their pivots 312, 312 until arrested by the stops 316, 316. During this movement the pawls 338, 338 by which the sleeves 320, 320 are held depressed are automatically released. For this purpose, at the left-hand side of the machine a rod 344 (Fig. 5) is pivoted at 345 to a part fixed on the table 20, for example to the stop 316, the pivot 345 being spaced laterally from the pivot 312 so that there will be relative movement between the upper end of the rod 344 and the bracket 310. As shown in Fig. 1, the rod 344 engages under a half conical formation on the end of a lever 346 pivoted between its ends to ears 348 on the bracket 310 and having its other end arranged to engage the upwardly projecting portion 340 of the sleeve holding pawl 338. When the bracket 310 swings outwardly the lever 346 has sufficient bodily movement lengthwise of the rod 344 to cause the half conical end of the lever to be cammed outwardly to release the pawl, whereupon the sleeve 320 will be raised by its spring 326 to the extent permitted by the slot 329. At the right-hand side of the

machine similar mechanism is provided for releasing the other sleeve holding pawl 338.

To locate the box 28 on the table 20, the box is provided at the left rear corner with an L-shaped leg 350 (Fig. 3), the horizontal part of which engages under a lug 352 (Fig. 5) secured to the table 20. At the right-hand end of the box are two reversely L-shaped legs 354 which engage under a flange 356 formed on a bar secured to the table 20. This construction, of course, prevents upward movement of the box with respect to the table. The box is guided into engagement with the lug 352 and the flange 356 and is located longitudinally by oppositely inclined surfaces 358, 360 formed on blocks secured to the table 20. If the box is too far to the left when placed upon the table, it will, when pushed rearwardly, be moved to the right by the inclined surface 358 and if it is too far to the right the surface 360 will act reversely to move it toward the left. The rearward position of the box is determined by upright pins 362. The box positioning means described not only locates the box so that the yokes will be brought into proper relation to the last depressing plunger 25 but also locates the box in proper relation to mechanism for applying the final pressure to the sole, which will now be described.

The bottom of the box 28 (Fig. 3) has an upwardly movable portion 366 which, when the box is positioned as described, overlies a plunger 368 which extends upwardly through the table 20. The plunger is pivoted to a lever 370 at a point nearer one end of the lever than the other so that the lever has unequal arms. The end of the longer arm of the lever 370 is fulcrumed at 372 to ears secured to the under side of the table. The shorter arm of the lever 370 is pivoted at 374 to the shorter arm of an unequal armed lever 376 fulcrumed at 378 between its ends to ears secured 40 to the under side of the table 20 and having the end of its longer arm connected by a link 380 (Fig. 1) to an unequal armed lever 382 between its ends. The end of the shorter arm of the lever 382 is fulcrumed on a rod 384 extending between ears 386 secured to the left-hand legs 22 of the table and on its longer arm a heavy weight 388 is suspended. The arrangement is such that descent of the weight by gravity acts, through the powerful compound leverage described, to raise 50 the plunger 368 which pushes upwardly on the movable portion 366 on the bottom of the box 28. This causes distortion of the bottom 33 of the vessel 30 and, since the vessel is confined at its sides by the walls of the box 28 and at the top 55 by the shoe sole, the pressure produced by operation of the plunger 368 will be transmitted through the liquid contained in the vessel to the bottom of the sole. The parts are preferably so proportioned and the plunger movement is such 60 that pressure of the order of seventy pounds per square inch may be applied to the sole.

When a smaller shoe is being treated a less area of the exposed wall 31 of the vessel 30, that is of the dilatable member, is covered by the sole and hence there will be more upward deflection of the wall 31 about the periphery of the sole, particularly at the ends of the shoe. This dilation may be so great as materially to reduce the pressure per square inch which can be applied to the shoe by the amount of distortion of the bottom 33 for which the machine is designed. To overcome these conditions means is provided for controlling the dilation of the dilatable member, that is, the top wall 31 of the vessel. It will be understood that the length variation in shoes is

much greater than the width variation, and that therefore it is unimportant as a practical matter to control the dilation of the member 31 at the sides of the shoe. Therefore, as illustrated, means for controlling the relation of the member 31 at the ends of the shoe only is provided. For this purpose masking-off plates 390, 392 (Figs. 1 and 10) are provided which are arranged to slide lengthwise of the shoe beneath the cover 32 of the box and over the surface of the dilatable member 31. The plates 390, 392 have their inner ends curved to correspond approximately to the shape, respectively, of the toe and heel ends of the shoe. By adjusting these plates inwardly when a small shoe is being treated, the amount of deflection of the top wall 31 of the vessel 30 may be controlled at the ends of the shoe, with the result that the pressure per square inch applied to a small sole will be substantially the same as that applied to a large sole. The construction and arrangement of the heel plate 392 is clearly shown in Fig. 10. At its inner end the plate 392 has downwardly turned lugs 394 which engage between the side walls of the vessel 30 and the side walls of the box 28. The outer end of the plate 100 has a narrow portion 396 which extends through a slot in the end of the box 28 as a flange 398 by which the plate 392 may be conveniently adjusted lengthwise of the pad 31. The toe plate 390 is of similar construction and is similarly arranged at 105 the opposite end of the box 28.

It is, of course, desirable that a large number of pads and pad boxes with their attendant shoe holding devices be provided with each machine, and that, after the sole has been put under pressure in the manner described, such pressure may be maintained unaltered for an indefinite time, the pad box and the shoe being removed from the machine and set aside for the cement to dry and another pad box placed in the machine for operation on another shoe. It is necessary, therefore, to provide on the pad box means to maintain the movable portion 366 of the bottom of the box in the position in which it was placed by operation of the plunger 368 and thus to maintain the pressure. For this purpose mechanism shown particularly in Figs. 10 to 13 is provided.

The movable portion 366 of the bottom of the box 28 is provided with a projection 400 the lower end of which is engaged by the plunger 368 and the front and rear sides of which are inclined downwardly and toward each other to form a wedge (Fig. 12).

Pivoted at 402 to the bottom of the box 28 is a lever 404 (Fig. 11) which between its ends has a 130 notch 405 which engages one side of the wedge 400. A similar notched lever 406 is similarly pivoted to the bottom of the box and engages by its notch the opposite side of the wedge 400. The notches 405 in the levers prevent movement of 135 the wedge 400 and hence of the movable portion 366 lengthwise of the levers 404, 406. The levers 404, 406 are urged toward each other by a spring 408 connected between them. To lock the levers in engagement with the wedge 400 means for 140 locking together the outer ends of the levers is provided, as best shown in Figs. 10 and 13. The outer ends of the levers 404, 406 pass through a slot in the end of the box 28 and are supported by a flat surface 409 formed on a part of the box 145 28. A member 410 is fixed to the free end of the lever 404, and to the member 410 is pivoted at 412 an arm 414 in which is arranged a slide 416. The slide is urged outwardly of the arm by a spring 418 mounted in the slide between its outer 150

end and a pin 420 fixed to the arm 414. On the upper face of the slide 416 are teeth 422 with which a spring-operated pawl 424 mounted on the arm 414 cooperates to hold the slide when it is pushed inwardly against outward movement. At the time when the wedge is to be locked, the plunger 368 will be applying upward pressure to the wedge 400 and the levers 404, 406 will be closed against the wedge by the spring 408. The arm 414 will be swung toward the lever 406 by a spring 426 suitably connected about its pivot 412 to swing the arm toward the box 28, the pawl 424 having been released to permit the slide 416 to be moved outwardly by the spring 418. To lock the wedge 400 the operator hooks a finger over a pin 428 on the arm 414 and pushes the slide 416 inwardly with his thumb, the pawl 424 of course holding it. The inner end of the slide 416, which preferably is wedge shaped as illustrated, is first engaged with a flat surface 429 on the lever 406 and holds the levers closed upon the wedge. Then by swinging the arm 414 toward the box the wedge-shaped end of the slide 416 is forced over a cammed surface 430 on the lever 406 until it rests on another flat surface 431 on the lever 406, movement of the arm 414 being then arrested by a stop pin 433 on the lever. This construction and mode of operation insure that if full pressure of the levers against the wedge is not secured by movement of the slide 416 because of the space between the teeth 422 on the slide, such pressure or more will be obtained by movement of the wedged end of the slide over the cammed surface 430 of the lever 406.

The pressure of the plunger 368 may now be released. This is done by operation of a treadle lever 432 (Fig. 1) fulcrumed at 434 on the rear leg 22 at the right-hand side of the machine and provided with a foot-piece 436. A chain 438 is connected to the lever 432 at one end, passes over a pulley 440 mounted on the table, and is connected at its other end to the lever 382. When the foot-piece 436 is depressed, the weight 388 is raised to relieve pressure on the plunger 368 and a spring 442 connected between the right front leg 22 and the pivot 374 between the levers 370, 376 operates to withdraw the plunger.

The treadle lever 432 is held in depressed position by locking means which, as illustrated, comprises a button 444 pivoted at 446 on the right front leg 22 and held in horizontal position by a spring 448. When the treadle lever is depressed the button 444 will turn to permit the lever to pass below it, whereupon it is restored to horizontal position by the spring 448. To prevent turning of the button in response to upward movement of the lever 432 when released, a latch is provided which comprises an angle lever 450 pivoted at 452 beneath one end of the button 444 and held by a spring 454 so that one arm of the angle lever engages that end of the button 444 to prevent its turning in response to upward pressure of the lever 432. The other arm of the angle lever 450 is compressible by pressure of the foot to release the button and permit descent of the weight 388 when desired. This construction enables the lever which holds the weight raised to be readily released notwithstanding the pressure of the lever on the button 444.

The weight 388 may be tripped off by releasing the latch 450 before the treadle 198 is depressed, that is, while the sole holding and shoe positioning devices are in operative position on the pad, in which case the weight 388 is utilized to with-

draw the sole holding and shoe positioning devices from their position over the pad and the resistance of the smaller weights 166, 262 is utilized to prevent too sudden application of force to the plunger 368. To this end a rod 456 is pivoted to the treadle lever 190 and passes upwardly through a hole in a lug 458 secured to the lever 382. On the rod 456 a sleeve 460 is adjustably held and located on the rod between the sleeve 460 and the lug 458 is a helical spring 462 surmounted by a collar 463, the spring being of sufficient strength to cause partial depression of the lever 190 when the weight 388 is released, as shown in Fig. 2, and consequently causing withdrawal of the sole holding and shoe positioning devices from their operative position over the pad. The compression of the spring 462 is released and the sole holding and shoe positioning devices fully withdrawn by further depression of the treadle 198 to its locked position, the full force of the weight 388 being then applied to the plunger 368.

The vessel 30, the top wall 31 of which has been hereinbefore referred to as the pad or dilatable member and the bottom wall 33 of which has been referred to as the distortable member, is preferably shaped and constructed as shown in Fig. 17. The side, end and bottom walls are, of course, confined by the box 28 the cover 32 of which confines the margin of the top wall 31 surrounding a sole-shaped area exposed by an opening in the cover. The top wall 31 has a longitudinal contour corresponding substantially to the longitudinal contour of the bottom of a shoe. The part on which the forepart of the shoe rests and the part on which the heel-seat portion of the shoe rests are substantially flat. These parts, however, are not in parallel planes but are inclined to each other substantially at the angle between the plane of the forepart and the plane of the heel-seat of an average shoe of the kind being made, for example a woman's shoe.

The two comparatively flat end portions of the wall 31 are connected by a shank portion 35 which is normally convex both transversely and longitudinally. This portion is readily compressible by pressure of the shank portion of a sole against it and is by such pressure made to assume a transversely concave curvature where engaged by the shank of the sole, the portions at each side of the shank being made to assume transversely convex curvatures. When the portions of the dilatable member under the shank and at each side thereof have been made to assume the described contour the shank portion 35 is distorted outwardly or dilated to cause the sole to be wrapped about the shank portion of the shoe and brought close to the upper at its margin either by external pressure produced by depressing the shoe upon the dilatable member, or by internal hydrostatic pressure produced by distorting the bottom wall 33 of the vessel, or both, in the manner described.

One suitable material of which to form the vessel is soft vulcanized rubber. In making it of rubber, sheets of rubber composition may be wrapped about a frangible core to form walls of suitable thickness and then the whole vulcanized in a suitable mold. The core may be broken up and removed through an opening cut in one of the walls. In Fig. 17 an opening made for removing the core is indicated at 468. This opening may be closed in any suitable manner, for example by applying a metal plate 470 (Fig. 3) over the opening inside the vessel and securing the

plate by bolts extending through the plate, through holes in the vessel adjacent to the opening 468 and through the bottom of the box 28. The end of the vessel (Fig. 17) is shown as having two holes 472, 473, in one of which a filling tube 474 (Fig. 3) is provided and to the other of which a pressure gage 476 is connected.

The vessel is completely filled with water through the filling tube 474, all air bubbles being removed, and then by pressing on the wall 31 a portion of the water is caused to flow out and a cap screwed onto the filling tube hermetically to seal the vessel. The wall 31 is then undistended and flabby, and, though the vessel is still full of water, the wall 31 is readily responsive to and deformable by manual pressure of the sole upon it, particularly at the shank portion.

If rubber alone were used to form a dilatable member of the thickness shown, it might under the pressure required stretch and bulge up too much in the space about the periphery of the sole where the member is unconfined. Hence a sheet of canvas or other suitable fabric is introduced between the plies of rubber composition of which the upper wall 31 of the vessel is built up before vulcanization, as indicated at 478 in Fig. 17. This construction permits the required distortion of the shank portion 35 of the wall 31 to cause it to wrap the sole about the shank portion of the shoe, particularly because of the contour which this portion assumes when the sole is preliminarily pressed upon it and prevents stretching or extension of the material and too much bulging of the member 31 at the sides of the shank and at other unconfined portions thereof about the shoe sole.

In order further to control deformation of the member 31 at the forepart and heel part when small shoes are being treated as well as to prevent the margin of the sole of these or larger shoes from being bent toward the upper too far as, for example, when a substantially flat forepart or heel part is desired, metal inserts may be incorporated into the material of which the member 31 is composed. Such metal inserts are shown at 480 and 482 in Fig. 17. The inserts 480, 482 may, for example, be plates of spring steel about .020 of an inch thick. The heel plate 482 is preferably intact except for a series of openings 484 in its marginal portion through which rubber is forced during the vulcanizing process to cause the layers of rubber above and below the plate to be bonded together and the plate retained in place. The forepart plate 480 is preferably slit or slotted longitudinally along its central line at 486 and has slits or slots 488 extending outwardly substantially radially from the point where the center of the toe of a sole will be located on the pad. Slits or slots 490 are also made substantially perpendicular to the central line 486 in the region where the ball portion of the sole will engage the pad. The plate having the slits 490 diminishes the transverse flexibility of the pad 31, that is, the facility with which it may be bent about axes extending lengthwise of the shoe and pad, without altering to the same extent its longitudinal flexibility, that is, the facility with which it may be bent about axes extending across the pad from side to side, and the radial slits 488 enable the portion of the pad 31 which is engaged by the toe of the sole to conform to the shape usually required at that portion of the sole.

In case uniform longitudinal flexibility in connection with uniform transverse stiffness is re-

quired, the form of forepart plate shown in Fig. 18 may be employed. In this case slots or slits 492 are made in the plate extending from side to side of the pad, the slots being parallel to each other and equally spaced. In both Figs. 17 and 18 the slits in the forepart plates have at their ends holes or enlargements 494 to enable the upper and lower layers of rubber to be bonded together and to prevent the slits from being extended by cracks through the margin of the plate.

The projection of the sole beyond the upper at the ball line not only varies in different styles of shoes but is different at the two sides of a shoe. In a pair of shoes the greater projection is on the outer sides of the shoes. If an operator receives for the application of soles first a batch of right shoes and then a batch of left shoes, the time required for making the necessary relative adjustments of the members 95, 96 is not great, but when operating under conditions where first a right shoe and then a left shoe has to be operated upon a construction by which relative adjustment of the members 95, 96 may be effected simultaneously at the two sides of the shoe is advantageous.

Such a construction is shown in Figs. 19 and 20 where the heads of the studs 108, by turning of which the members 96 are adjusted relatively to the members 95, are formed as pinions 496 with which rack bars 498 mesh. The bars 498 are held in mesh with the pinions 496 by plates 500 secured to the bars and having slots 502 which engage reduced portions of the studs 108. A lever 504 is pivoted on the stud 74 and has a portion extending inwardly of its pivot 74 formed as a toothed segment 506 with which a similar toothed segment 508 mounted on the stud 75 meshes. One of the rack bars 498 is connected at 510 to the segment 508 and the other rack bar 498 is connected at 512 to the lever 504, the distance from the pivot 510 to the pivot 75 of the segment 508 being equal to the distance from the pivot 512 to the pivot 74 of the lever 504. By movement of the lever 504 the rack bars 498, 498 are moved equally and oppositely to effect equal and opposite adjustment of the members 96 relatively to the members 95. It will be understood that the positioning members 97, 98, which engage the sole and shoe in the vicinity of the tip line, may be used with this construction though they have been omitted in Figs. 19 and 20 for the sake of clearness.

When the machine is to be operated, the parts will be in the condition shown in Fig. 1 except that the yoke 280 will be swung outwardly against its stop 286. The operator places at random upon the dilatable member 31 a sole to which, for example, pyroxylin cement has been applied, allowed to dry, and then cut with a solvent. He presses down upon the sole, causing the shape of the doubly convex shank portion of the member 31 to be changed to a transversely concave contour under the sole and to a transversely convex contour at each side of the sole. The operator then releases the latch 200 and permits the weights 166, 262 to move the feelers and shoe gages from their positions withdrawn from the pad to their positions over the pad. The slides 53 and 54 will be arrested by their respective stops 174 and 271, and the cam bars 164, 260 will have allowed the positioning members to drop into engagement with the pad. During the inward movement of the slides the bars 114 and 222 will have engaged the toe and heel ends 150

of the sole respectively and will have had their movement arrested by the sole. The feelers 98, 96, 252 will next be closed upon the sole by the inward movement of the cam plates 80, 82, 5 216, due to their operating springs 148, 144, 227, and the bars 114 and 222 will be locked against outward movement. The sole will now be held in the position in which the operator placed it. If either one of either pair of feelers reaches the 10 sole before the other one of that pair, its movement will be arrested and the cam plate which operates that pair will swing on its pivot and continue its inward movement to cause the other one of the pair to engage the sole, each pair 15 being then locked by the inclined slots in the cam plates against relative movement of separation. If the operator now finds that either end, or both ends, of the sole should be shifted transversely of the pad in either direction, he can 20 so shift the sole, while the sole is still held, by applying lateral pressure to any one of any pair of feelers or to the corresponding shoe gages.

The sole having been properly located, a shoe to which the sole is to be attached and which 25 also has cement applied to its bottom is slipped under the toe engaging plunger 290 and allowed to rest upon the sole. Then, assuming that the proper relative adjustment of the sole engaging members or feelers 96, 98, 252, and the shoe 30 engaging members or gages 95, 97, 250 have been made by turning the eccentric studs 108, 253, the shoe will be properly located with respect to the sole by the act of placing the shoe on the sole.

The operator will now grasp one of the levers 35 334 in each of his hands and swing the brackets 310, 310 in the vertical position, the yokes 280, 294, or either of them, being by this movement swung to vertical position over the two ends of the shoe, if not previously so located, by the lugs 342 40 on the brackets 310. By depressing the levers 334, the sleeves 320 are pushed down and the plungers 284, 290 brought into engagement with the last and shoe respectively. The levers 334 are then swung over toward the operator to 45 cause the plungers 322, 322 to be operated by the cam faces 336, 336. If more preliminary pressure is desired at either end or both ends of the shoe, one or both of the levers 334 will be thrown up, the sleeve 320 again depressed, and 50 the lever again operated to increase the pressure, the pawl 304 of course retaining such pressure. When the operator has obtained the desired preliminary pressure, which may be in the vicinity of twenty pounds per square inch, the levers 55 334, 334 are thrown back and, since the plungers 322, 322 are lifted by their springs 326, 326, the brackets are free to be swung back to the position shown in Fig. 1. This they tend to do by gravity, the weight of the brackets being so distributed with respect to their pivots 312 that they 60 tend to swing outwardly away from each other. As they swing outwardly, the levers 346 are operated by the rods 344 to release the sleeve holding pawls 338 and the springs 326 act to raise the sleeves 320.

The shoe is now ready to have the final pressure applied thereto and the operator trips the latch 450 to permit the weight 388 to act on the plunger 368. As the weight descends, the lug 70 458 on the lever 382 operates through the spring 462 to withdraw the cam plates 80, 82, 216, to release the feelers and gages from the shoe, and partially to withdraw the slides 53 and 54. This operation insures that the feelers and gages will 75 be withdrawn from their operative position to a

position where they cannot interfere with the application of final pressure to the shoe sole. During the withdrawal of the cam plates 80, 82, 216, they are restored to central position by engagement of the pins 150, 146, 229 with the bell-mouthed notches in their respective relocating plates 62, 68, 212. The operator now completes the withdrawal of the slides by depression of the treadle 198, thus relieving the compression of the spring 462 and permitting the full force of the weight 388 to be applied to the plunger 368. The action of the plunger distorts the bottom wall of the vessel to apply final pressure to the shoe by forcing upwardly the movable bottom 366 of the box. The operator then operates the slide 80 416 and the arm 414 in the manner described to lock the pressure retaining levers 404, 406 against the wedge member 400. The operator next depresses the foot piece 436 to raise the weight and release the pressure on the plunger, whereupon 85 the pad box with its attendant mechanism for retaining the shoe under pressure may be removed from the machine and set aside for the time required for the cement to set and another pad box placed in the machine to receive the 90 next shoe. When the shoe is to be released from the pad, the arm 414 is forced outwardly by hand or by a suitable implement, thus releasing the wedge 400. The shoe now being under only the 95 preliminary pressure, the pawls 304, 304 are then 100 readily released by pressing on the upwardly projecting portions 308, 308 to release the pressure completely and permit the shoe to be removed.

Having thus described my invention, what I 110 claim as new and desire to secure by Letters Patent of the United States is:

1. In a machine for use in the manufacture of shoes, the combination of a pad to receive a sole of any size placed by the operator at random in any one of an indefinite number of operative positions, and feelers constructed and arranged to engage the edge face of the sole on the pad only at points in the vicinity of the ends of the tip line end of the ends of the ball 115 line, said feelers coming to rest without disturbing the position of the sole and acting to hold it against movement in its own plane.

2. In a machine for use in the manufacture of shoes, the combination of a pad to receive a sole 120 of any one of a series of sizes, which sole may be placed by the operator on the pad at random, and feelers constructed and arranged to engage the sole only at points in the vicinity of the ends of the tip line and of the ends of the ball line and 125 maintain the sole in the position in which it happens to have been placed.

3. In a machine for use in the manufacture of shoes, the combination of a pad upon which a sole of any size may be placed at random by the 130 operator, and means acting irrespectively of the position of the sole to engage said sole and to hold it in the position in which it was placed, said means being constructed and arranged to permit the bottom of a shoe to be placed in contact with 135 the exposed face of the sole while the sole is so held.

4. In a machine for use in the manufacture of shoes, the combination of a pad upon which a sole of any size may be placed in a position selected by the operator, feelers acting irrespectively of the position of the sole to find the periphery of the sole at the toe end of the sole and on opposite sides of the forepart of the sole 145 while the sole is in said selected position, and 150

- means for locking said feelers against relative movement with respect to the sole.
5. In a machine for use in the manufacture of shoes, the combination of a pad upon which a sole may be placed in any one of a number of positions at the selection of the operator, members acting irrespectively of the position of the sole to engage the periphery of the sole at an end of the sole and on opposite sides of the sole while the sole is in said selected position, and means to lock said members against outward movement away from the sole.
6. In a machine for use in the manufacture of shoes, the combination of a pad upon which a sole is placed in a position selected by the operator, members movable inwardly toward the sole to engage the periphery of the sole at a plurality of points on each side of the sole, and means to hold said engaging members against outward movement with respect to the sole, said engaging members being constructed and arranged to be shifted in the plane of the sole on the pad while they are held against relative movement away from the sole.
- 25 7. In a sole laying machine, the combination of a pad upon which a sole may be placed in a position selected by the operator, means for engaging the periphery of the sole irrespectively of its position at salient points on opposite sides of the sole, and means for locking said engaging means in engagement with the sole to hold it in said selected position.
8. In a machine for use in the manufacture of shoes, the combination of a pad upon which a sole is placed by the operator, feelers constructed and arranged to engage the periphery of the sole at a plurality of points on each side of the sole, and means to lock said feelers against outward movement away from the sole, said feelers being constructed and arranged to permit bodily shifting of the sole on the pad while they are locked against relative movement away from the sole.
9. In a machine for use in the manufacture of shoes, the combination of a pad upon which a sole may be placed at random by the operator, and means acting irrespectively of the position of the sole for engaging the edge face of the sole so placed at points adjacent to the ends of the tip line and adjacent to the ends of the ball line to hold the forepart of the sole in the position in which it was placed.
10. In a machine for use in the manufacture of shoes, the combination of a pad upon which a sole is placed in a position selected by the operator, and means for engaging the edge face of the sole so placed at points on the two sides of the toe end and adjacent to the ends of the ball line normally to hold the forepart of the sole in the selected position, said holding means being constructed and arranged to be shiftable in the plane of the sole by the operator to enable the position of the sole on the pad to be changed.
11. In a machine for use in the manufacture of shoes, the combination of a pad upon which a sole is placed by the operator, a pair of feelers for engaging the edge face of the sole so placed at points adjacent to the ends of the tip line, means for holding said feelers against separation, a pair of feelers for engaging the edge face of the sole at points adjacent to the ends of the ball line, and means for holding the ball line engaging feelers against separation, said holding means being constructed and arranged to permit shifting by the operator of the two pairs of feelers relatively to each other in the plane of the sole.
12. In a machine for use in the manufacture of shoes, the combination of a pad upon which a sole is placed by the operator, means for engaging an edge face of the sole so placed at points adjacent to the ends of the tip line, means for holding the tip line engaging means against separation, means for engaging the edge face of the sole at points adjacent to the ends of the ball line, and means for holding the ball line engaging means against separation, said holding means being constructed and arranged to permit shifting of the ball line engaging means relatively to the tip line engaging means and vice versa, transversely of the sole, to permit orientation of the sole on the pad.
13. In a machine for use in the manufacture of shoes, the combination of a pad upon which a sole is placed by the operator, members for engaging the edge face of the sole so placed at points adjacent to the ends of the tip line and adjacent to the ends of the ball line, and a member to engage the toe end of the sole, said toe end engaging means being constructed and arranged to prevent forward endwise movement of the sole and said tip line and ball line engaging members being constructed and arranged for relative lateral shifting movement in the plane of the sole to permit orientation of the sole on the pad.
14. In a sole laying machine, the combination of a pad upon which a sole is placed by the operator, a pair of members for engaging the edge face of the sole so placed at points adjacent to the ends of the tip line, and a pair of members for engaging the edge face of the sole at points adjacent to the ends of the ball line, said members normally holding the forepart of the sole in the selected position, each pair of members being constructed and arranged to be shiftable laterally of the pad in the plane of the sole end by the operator to enable the lateral position of the sole on the pad to be changed while still held by said members.
15. In a machine for use in the manufacture of shoes, the combination of a pad upon which a sole is placed by the operator, a pair of members engaging the edge face of the sole so placed at points adjacent to the tip line, means for holding said members against separation, a pair of members for engaging the edge face of the sole at points adjacent to the ends of the ball line, and means for holding the ball line engaging members against separation, each pair of members being constructed and arranged for movement in the plane of the sole laterally of the pad in either direction to permit orientation of the sole in the plane of the sole while held by said members.
16. In a machine for use in the manufacture of shoes, the combination of a pad upon which a sole is placed, levers having members at their ends to engage the periphery of the sole at points on opposite sides of the sole, a plate having inclined slots, and pins on the levers engaging said slots, said plate acting to operate and to lock said levers and thereby hold said members against the sole.
17. In a machine for use in the manufacture of shoes, the combination of a pad upon which a sole is placed, members to engage the periphery of the sole at points on opposite sides of the sole, levers on which said members are mounted, a plate having inclined slots acting on said levers to close said members against the sole and lock them against outward movement with respect to the sole, and a pivot on which said plate can

swing to permit shifting of the members on the pad while they are locked against the sole.

18. In a machine for use in the manufacture of shoes, the combination of a pad upon which a sole is placed, members for engaging an edge face of the sole as placed at points adjacent to the ends of the tip line and adjacent to the ends of the ball line, levers upon which said members are mounted, and slotted plates movable relatively to the levers and acting to hold said members in engagement with the sole.

19. In a machine for use in the manufacture of shoes, the combination of a pad upon which a sole is placed, a pair of members for engaging the edge face of the sole as placed at points adjacent to the ends of the tip line, a pair of members for engaging an edge face of the sole at points adjacent to the ends of the ball line, and levers each carrying one of said members, and a sliding plate for each pair of levers movable relatively thereto to operate the levers and thereby to cause said members to hold the forepart of the sole as placed, said plates being constructed and arranged to permit each pair of members to be shifted laterally in the plane of the sole end by the operator to enable the position of the sole on the pad to be changed while so held.

20. In a machine for use in the manufacture of shoes, the combination of a pad upon which a sole is placed, a pair of members for engaging the edge face of the sole as placed at points adjacent to the ends of the tip line, a pair of members for engaging an edge face of the sole at points adjacent to the ends of the ball line, levers each carrying one of said members, and a sliding plate for each pair of levers movable relatively thereto to operate the levers and thereby to cause said members to hold the forepart of the sole as placed, said plates being pivoted for swinging movement in a plane parallel to the plane of the forepart of the sole to permit each pair of members to be shifted laterally of the sole in either direction and thus to enable the position of the sole on the pad to be changed while still grasped by said members.

21. In a machine for use in the manufacture of shoes, the combination of a pad upon which a sole is placed, a pair of members for engaging an edge face of the sole as placed at points adjacent to the tip line, levers carrying said members, means for locking said levers to hold the members against separation, a pair of members for engaging the edge face of the sole at points adjacent to the ends of the ball line, levers carrying said members, and means for locking said levers to hold the members against separation, the locking means for each pair of levers being constructed and arranged to permit shifting of the levers with their sole engaging members in the plane of the sole relatively to the other pair of levers.

22. In a machine for use in the manufacture of shoes, the combination of a pad upon which a sole is placed in a position selected by the operator, means for engaging the toe end of the sole, means for engaging opposite sides of the forepart of the sole at a plurality of points, means for engaging opposite sides of the heel end of the sole, and means for locking said shoe engaging means against outward movement with respect to the sole, all of said side engaging means being constructed and arranged to permit bodily shifting movement of the sole on the pad while they are locked against outward movement with respect to the sole.

23. In a machine for use in the manufacture of shoes, the combination of a pad upon which a sole is placed in a position selected by the operator, members operable to engage the edge face of the sole so placed at points on opposite sides of the toe end of the sole and at points adjacent to the ends of the ball line to hold the forepart of the sole so placed, and separate members operable to engage the heel end of the sole at opposite sides thereof, said heel engaging members being constructed and arranged to be shifted in the plane of the sole and to enable the position of the rear end of the sole to be changed with respect to the position of the forepart of the sole.

24. In a machine for use in the manufacture of shoes, the combination of a pad upon which a sole is placed in a position selected by the operator, a member for engaging the toe end of the sole, pairs of members movable inwardly toward the sole to engage the periphery of the forepart of the sole at a plurality of points on opposite sides of the sole, means controlled by closing movement of one pair of members for locking the end engaging member against outward movement, and means for locking each pair of members against relative movement of separation.

25. In a machine for use in the manufacture of shoes, the combination of a pad to receive an unattached sole, members for engaging the sole at salient points on its periphery including points in the vicinity of the ends of the tip line and of the ball line, and other members directly superimposed upon said members for engaging corresponding points on the sides of the shoe to locate the shoe relatively to the sole.

26. In a machine for use in the manufacture of shoes, the combination of a pad to receive an unattached sole, feelers operable to engage the sole irrespectively of its position on the pad at points in the vicinity of the ends of the tip line and the ends of the ball line, and gage members superimposed on the ends of the feelers for engaging corresponding points on the shoe to locate the shoe relatively to the sole.

27. In a machine for use in the manufacture of shoes, the combination of a pad to receive an unattached sole, members for engaging the sole at salient points on its periphery including the toe end and points in the vicinity of the ends of the tip line, and other members directly superimposed upon said members for engaging corresponding points only on the side of the shoe to locate the shoe relatively to the sole.

28. In a machine for use in the manufacture of shoes, the combination of a pad to receive an unattached sole, feelers for engaging the sole at salient points on its periphery including the toe end and points in the vicinity of the ends of the tip line and the ends of the ball line, and gage members superimposed upon the ends of said feelers for engaging corresponding points on the shoe to locate the shoe relatively to the sole.

29. In a machine for use in the manufacture of shoes, the combination of a pad to receive a sole in any one of a number of positions as selected by the operator, means to engage the edge face of the sole while in the position so selected and acting to hold the sole in that position against movement in its own plane, and means for locating a shoe relatively to the sole while so held when the shoe is later placed by hand upon the sole.

30. In a machine for use in the manufacture of shoes, the combination of a pad to receive an unattached sole, feelers movable into and out

- of position over the pad for holding the sole on the pad against movement in a plane parallel to the surface of the pad, and means carried by said feelers for locating a shoe relatively to the sole 5 when the shoe is thereafter placed upon the sole. 80
31. In a machine for use in the manufacture of shoes, the combination of a pad to receive an unattached sole, members movable into and out of position over the pad for engaging the sole at salient points on its periphery including the end of the toe and points in the vicinity of the ends of the tip line, and other members superimposed upon said members for engaging corresponding points on a shoe to locate the shoe relatively to the sole. 85
32. In a machine for use in the manufacture of shoes, the combination of a pad to receive an unattached sole, feelers movable into and out of position over the pad for engaging the sole at salient points on its periphery including the toe end and points adjacent to the ends of the tip line and the ends of the ball line, and gage members arranged above the sole engaging members and moving therewith for engaging points on the shoe to locate the shoe relatively to the sole. 90
33. In a machine for use in the manufacture of shoes, the combination of a pad to receive an unattached sole, members movable to engage the sole at salient points only on its periphery, and other members carried by said members for engaging corresponding points on the shoe to locate the shoe relatively to the sole, said members being constructed and arranged to hold the sole down upon the pad. 95
34. In a machine for use in the manufacture of shoes, the combination of a pad to receive an unattached sole, members for engaging the sole at salient points only on its periphery including the toe end, and points adjacent to the ends of the tip line and the ends of the ball line, and other members superimposed on said members for engaging corresponding points on the shoe to locate the shoe relatively to the sole, said sole engaging members and shoe engaging members being relatively constructed and arranged to engage the margin of the upper face of the sole to hold it against upward movement. 100
35. In a machine for use in the manufacture of shoes, the combination of a pad to receive an unattached sole, members movable to engage the sole at salient points only on its periphery, and shoe engaging members carried by said sole engaging members for engaging corresponding points on the shoe to locate the shoe relatively to the sole, said shoe engaging members being arranged to overlie the projecting margin of the sole to hold the sole down upon the pad. 105
36. In a machine for use in the manufacture of shoes, the combination of a pad to receive an unattached sole, members movable to engage the sole at a plurality of points only about the periphery of the forepart, members for engaging the heel end of the sole at the two sides of the sole, and shoe engaging members carried by said members for engaging corresponding points on the shoe to locate the shoe relatively to the sole, said sole engaging members for the heel end of the sole having projecting lips arranged to engage the margin of the upper face of the sole to hold it against upward movement. 110
37. In a machine for use in the manufacture of shoes, the combination of a pad to receive a sole in a position selected by the operator, means to engage the edge face of the sole while in the 75 position so selected and acting to hold the sole against movement in its own plane, and means for locating a shoe relatively to the sole while so held, said sole engaging means and shoe locating means being relatively adjustable to accommodate the desired sole extension at different parts of the shoe. 115
38. In a machine for use in the manufacture of shoes, the combination of a pad to receive an unattached sole, members movable into position to engage a sole of any size at salient points on its periphery including the toe end and points adjacent to the ends of the tip line and the ends of the ball line, and other members superimposed on said members for engaging corresponding points on the shoe to locate the shoe relatively to the sole, each of said sole engaging members being adjustable relatively to its corresponding shoe engaging member to accommodate the desired sole extension at different parts of the shoe. 120
39. In a machine for use in the manufacture of shoes, the combination of a pad to receive an unattached sole, members movable on the pad to engage the sole at salient points on its periphery including the toe end and points adjacent to the ends of the tip line and the ends of the ball line, and other members superimposed on said members for engaging corresponding points on the shoe to locate the shoe relatively to the sole, said sole engaging members and shoe engaging members being relatively adjustable to accommodate the extension of the sole at points on the shoe where said extension is variable. 125
40. In a machine for use in the manufacture of shoes, the combination of a pad to receive an unattached sole, members for engaging the sole at salient points on its periphery including the toe end of the sole and points adjacent to the ends of the ball line, other members superimposed on said members for engaging corresponding points on the shoe to locate the shoe relatively to the sole, and means for effecting equal and opposite adjustments of the means for engaging the sole at the ball line relatively to their corresponding shoe engaging means to accommodate different degrees of sole extension at the two sides of the shoe. 130
41. In a machine for use in the manufacture of shoes, the combination of a pad to receive an unattached sole, feelers for engaging the sole at points adjacent to the ends of the ball line, gage members superimposed on said feelers for engaging corresponding points on the shoe to locate the shoe relatively to the sole, and means for effecting equal and opposite relative adjustments of the feelers and gage members at opposite sides of the sole to adapt the machine for use on right and left shoes having a greater extension of the sole on one side than on the other. 135
42. In a machine for use in the manufacture of shoes, the combination of a pad upon which a sole may be placed in any one of a number of positions as selected by the operator, a group of members movable into engagement with the edge of the sole in its selected position, and a group of gage members one connected to each of the first-named members moving with the latter into positions determined by the sole and formed and arranged to position a shoe relatively to the sole when the shoe is placed upon the sole. 140
43. In a machine for use in the manufacture of shoes, the combination of a pad upon which a sole is placed in a position selected by the operator, members constructed and arranged to engage the edge of the sole at a plurality of points 145

- on each side of the sole, means to lock said sole engaging means against outward movement away from the sole constructed and arranged to permit bodily shifting of the sole and the sole engaging members relatively to the pad, and a group of shoe positioning gage members, one carried by each of the sole engaging members, formed and arranged to position a shoe relatively to the sole. 5
44. In a machine for use in the manufacture of shoes, the combination of a pad upon which a sole is placed in a position selected by the operator, a group of levers each provided at one of its ends with a member for engaging an edge face of the sole, pairs of the sole engaging members being arranged to engage the edge of the sole on the pad at points adjacent to the ends of the tip line and to the ends of the ball line respectively and to be positioned by the sole, and a group of gage members, one connected to each of the sole 10 engaging members, arranged to be positioned by the sole engaging members and themselves to position a shoe relatively to the sole. 15
45. In a machine for use in the manufacture of shoes, the combination of a pad upon which a sole is placed in a position selected by the operator, a group of feelers movable into engagement with the edge of the sole in its selected position, and a group of gage members, one connected to each of the feelers, moving with the feelers into positions determined by the sole and formed and arranged to position a shoe relatively to the sole. 20
46. In a machine for use in the manufacture of shoes, the combination of a pad upon which a sole is placed in a position selected by the operator, feelers constructed and arranged to engage the edge of the sole at a plurality of points on each side of the sole, means to lock said feelers against outward movement away from the sole constructed and arranged to permit bodily shifting of the sole and the feelers relatively to the pad, and a group of shoe positioning gage members, one carried by each of the feelers, formed and arranged to position a shoe relatively to the sole. 25
47. In a machine for use in the manufacture of shoes, the combination of a pad upon which an unattached sole is placed, sole holding means initially withdrawn from the pad, and means for moving said holding means over the pad to cause said holding means to find the sole in the position in which it is placed and to hold the sole against movement in its own plane. 30
48. In a machine for use in the manufacture of shoes, the combination of a pad upon which an unattached sole is placed by the operator, and sole holding means movable from a position in which they are not over the pad to a position over the pad from both ends thereof to engage the sole in the position in which it was so placed and to hold both ends of the sole against movement in the plane of the sole. 35
49. In a machine for use in the manufacture of shoes, the combination of a pad on which an unattached sole is placed, a pair of sole engaging members movable from a position away from the pad to a position thereon adapted to engage the edge face of the sole at opposite points on the forepart thereof, a pair of sole engaging members movable from a position away from the pad to a position thereon and adapted to engage the edge face of the sole at opposite sides of the rear portion thereof, and means for preventing relative separation of the members of each pair, said means being constructed and arranged to permit movement of each pair of members 40
- laterally of the pad in response to pressure to permit change of location of the sole on the pad while still held by said members. 45
50. In a machine for use in the manufacture of shoes, the combination of a pad upon which an unattached sole is placed by the operator, sole holding means initially withdrawn from over the pad, and means for moving said holding means over the pad and for causing said holding means to find the sole in the position in which it is placed by the operator and to hold the sole in said position against lateral and forward movement. 50
51. In a machine for use in the manufacture of shoes, the combination of a pad upon which an unattached sole is placed by the operator, a plurality of feelers initially withdrawn from the pad, and means for moving said feelers over the pad and for causing them to find the sole in the position in which it is placed by the operator and to hold the sole positively against forward movement and frictionally against lateral movement. 55
52. In a machine for use in the manufacture of shoes, the combination of a pad upon which an unattached sole is placed by the operator, and feelers initially withdrawn from a position over the pad and movable from their initial position into position over the pad from each end thereof to engage the toe end of the sole and the edge 100 face of the sole at opposite sides thereof adjacent to opposite ends of the sole. 105
53. In a machine for use in the manufacture of shoes, the combination of a pad upon which an unattached sole is placed, and sole holding means movable over the pad from each end thereof to engage the toe end of the sole and the edge face of the sole at opposite sides thereof adjacent to opposite ends of the sole, said edge face engaging means being movable against substantial friction to enable the location of the sole on the pad to be shifted laterally of the pad. 110
54. In a machine for use in the manufacture of shoes, the combination of a pad upon which an unattached sole is placed, a member for engaging the toe end of the sole, a pair of sole engaging members, said members being movable from a position away from the pad to a position thereon and adapted to engage the edge face of the sole at the end and at opposite points on the forepart 115 thereof, a pair of sole engaging members movable from a position away from the pad to a position thereon and adapted to engage the edge face of the sole at opposite points at the rear portion thereof, means for locking the toe end engaging 120 member against movement away from the sole, and means for preventing relative separation of the members of each pair. 125
55. In a machine for use in the manufacture of shoes, the combination of a pad upon which an unattached sole is placed, feelers at the ends of the pad, initially withdrawn from over the pad, and means for moving said feelers over the pad constructed and arranged to cause them to find the sole in the position in which it is placed on the pad and to hold the ends of the sole against lateral movement from that position. 130
56. In a machine for use in the manufacture of shoes, the combination of a pad upon which an unattached sole is placed, sole holding means one 135 at each end of the pad, initially withdrawn from the pad, and means for moving both said holding means simultaneously over the pad and for causing said holding means to confine the sole with its ends in the position in which they are placed on 140
- 75

- the pad and to hold the sole frictionally against lateral movement, the holding means at the ends of the pad being constructed and arranged to be shifted against frictional resistance in either direction laterally of the pad.
57. In a machine for use in the manufacture of shoes, the combination of a pad upon which an unattached sole is placed, sole holding means initially withdrawn from over the pad and movable from its initial position into position over the pad from the ends thereof, one holding means operating to engage the toe end of the sole and the edge face of the sole at opposite sides thereof and the other holding means operating to engage opposite sides of the heel end of the sole, and means for moving both holding means into and out of operative position.
58. In a machine for use in the manufacture of shoes, the combination of a pad upon which an unattached sole is placed, forepart holding means initially withdrawn from position over the pad and movable from its initial position into position over the pad from one end thereof to engage the toe end of the sole and the edge face of the sole at opposite sides of the forepart thereof, and heel end holding means movable over the pad from the opposite direction to engage opposite edge faces of the rear end of the sole.
59. In a machine for use in the manufacture of shoes, the combination of a pad upon which an unattached sole is placed, forepart holding means movable over the pad from one end thereof to engage the toe end of the sole and the edge face of the sole at opposite sides of the forepart thereof, and heel end holding means movable over the pad from the opposite direction to engage opposite edge faces of the rear end of the sole, the means for engaging the sides of the forepart and the heel end holding means being movable against frictional resistance to enable the location of the sole on the pad to be shifted laterally of the pad.
60. In a machine for use in the manufacture of shoes, the combination of a pad to receive an unattached sole, means movable from a position in which it is not over or above the pad into a position over and above the pad for holding a sole placed on the pad, and means on said sole engaging means for locating a shoe relatively to the sole.
61. In a machine for use in the manufacture of shoes, the combination of a pad to receive an unattached sole, members movable into and out of position over the pad and constructed and arranged to close upon the sole at salient points on the periphery of its forepart including the toe end and opposite sides of the forepart, other members movable into and out of position over the pad for holding the heel end of the sole, and shoe engaging members carried by said sole engaging members for engaging corresponding points on the shoe to locate the shoe relatively to the sole.
62. In a machine for use in the manufacture of shoes, the combination of a pad to receive an unattached sole, members for engaging the edge face of the forepart of the sole at its end and on opposite sides thereof, members for engaging opposite sides of the heel end of the sole, means for holding all of said members against outward movement with respect to the sole, and shoe locating members controlled by said sole engaging members for engaging corresponding points on the shoe to locate the shoe relatively to the sole.
63. In a sole laying machine, the combination of a pad to receive an unattached sole, a member movable over the pad to engage the toe end of the sole and constructed and arranged to have its movement arrested by contact with the sole, members movable over the pad with said end engaging member and adapted to close upon the forepart of the sole at a plurality of points on opposite sides thereof, means operated by closing movement of said side engaging members for locking the end engaging member against outward movement with respect to the sole, members movable over the pad and adapted to close upon the heel end of the sole at opposite sides thereof, means for locking said side engaging members against outward movement with respect to the sole, and shoe positioning members superimposed upon said sole engaging members for engaging corresponding points on the shoe to locate the shoe relatively to the sole.
64. In a machine for use in the manufacture of shoes, the combination of a pad to receive an unattached sole, members movable over the pad into position to embrace the forepart of a sole, means for operating said members to cause them to close upon the sole and to engage the forepart of the sole at a plurality of points on each side of the sole, heel end engaging members movable over the pad in position to embrace the heel end of the sole, means for closing said members to engage the heel end of the sole at opposite sides thereof and to hold them against relative movement of separation, and shoe engaging members superimposed upon said sole engaging members for engaging corresponding points on the shoe to locate the shoe relatively to the sole, each of said sole engaging members being adjustable relatively to its corresponding shoe engaging member to effect the desired location of the sole relatively to the shoe at different points on the shoe.
65. In a machine for use in the manufacture of shoes, the combination of a pad upon which a sole is placed, feelers to engage the periphery of the sole, levers on which said feelers are mounted, a plate having inclined slots acting on said levers to close the feelers against the sole and lock them against outward movement with respect to the sole, a pivot on which said plate can swing to permit shifting of the feelers upon the pad, and means for restoring the levers and plates to normal central position after use.
66. In a machine for use in the manufacture of shoes, the combination of a pad to receive an unattached sole, members movable over the pad into position to embrace the forepart of a sole, means for operating said members to cause them to close upon the sole and to engage the forepart of the sole at a plurality of points on each side of the sole, heel end engaging members movable over the pad in position to embrace the heel end of the sole, means for closing said members to engage the heel end of the sole at opposite sides thereof and to hold them against relative movement of separation, shoe engaging members superimposed upon said sole engaging members for engaging corresponding points on the shoe to locate the shoe relatively to the sole, and means for automatically restoring the sole engaging members and shoe engaging members to normal central position as an incident to withdrawing said members from their position over the pad.
67. In a machine for use in the manufacture of shoes, the combination of a pad to receive an unattached sole, members for engaging the edge face of the forepart of the sole at a plurality of points on each side of the sole, means for closing said members to engage the edge face of the forepart of the sole at a plurality of points on each side of the sole, and means for automatically restoring the sole engaging members and shoe engaging members to normal central position as an incident to withdrawing said members from their position over the pad.

- points including points in the vicinity of the toe at opposite sides of the sole and points adjacent to the ends of the ball line, separate opposed members for engaging the edge face of the sole 5 at opposite sides of the heel end thereof, and shoe engaging members superimposed upon said sole engaging members for engaging corresponding points on the shoe to locate the shoe relatively to the sole, said sole engaging members 10 and shoe engaging members being relatively adjustable to accommodate the extension of the sole at points on the shoe where the extension is variable.
68. In a machine for use in the manufacture of 15 shoes, the combination of a pad to receive an unattached sole, members movable into and out of position over the pad and constructed and arranged for closing movement to engage the edge face of the forepart of the sole at opposite sides 20 of the toe and at points adjacent to the ends of the ball line, a member for engaging the toe end of the sole, said member being constructed and arranged to be positioned and locked by operation of said sole engaging means to hold 25 the sole against endwise movement, heel end engaging members movable into and out of position over the pad, means for operating said members to engage the heel end of the sole at opposite sides thereof, and shoe engaging members 30 carried by said sole engaging members for engaging corresponding points on the shoe to locate the shoe relatively to the sole.
69. In a machine for use in the manufacture of 35 shoes, the combination of a pad to receive an unattached sole, means movable longitudinally of the pad into and out of position over the pad for holding the forepart of a sole placed on the pad, means movable longitudinally of the pad into and out of position over the pad for engaging the rear 40 part of the sole, and means on said sole engaging means for locating a shoe relatively to the sole.
70. In a machine for use in the manufacture of 45 shoes, the combination of a pad to receive an unattached sole, feelers movable into and out of position over the pad for engaging the forepart of the sole at a plurality of points about its periphery, other feelers movable into and out of position over the pad for engaging the heel end of the sole at a plurality of points about its periphery, and 50 shoe positioning gage members carried by said sole feelers for engaging the shoe to locate the shoe relatively to the sole.
71. In a machine for use in the manufacture of 55 shoes, the combination of a pad to receive an unattached sole, members movable into and out of position over the pad for engaging the forepart of the sole at a plurality of points about its periphery, other members movable into and out of position over the pad for engaging the heel end of the sole at a plurality of points about its periphery, and shoe engaging members carried by said sole 60 engaging members for engaging the shoe to locate the shoe relatively to the sole, said heel end engaging members being shiftable laterally of the pad relatively to the forepart engaging members.
72. In a machine for use in the manufacture of 65 shoes, the combination of a pad upon which a sole is placed, members operable to engage the edge face of the sole so placed at points on opposite sides of the toe end of the sole and at points adjacent to the ends of the tip line to hold the forepart of the sole so placed, separate members operable to engage the heel end of the sole at opposite sides thereof, said heel engaging members being constructed and arranged to be shifted in 70 the plane of the sole and to enable the position of the rear end of the sole to be changed with respect to the position of the fore part of the sole, and means carried by said sole engaging members for locating a shoe with respect to the sole while the sole is so held.
73. In a machine for use in the manufacture of 75 shoes, the combination of a pad upon which a sole is placed, feelers to engage the periphery of the sole at points on opposite sides of the sole, levers on which said feelers are mounted, a plate having inclined slots acting on said levers to close said feelers against the sole and lock them against outward movement with respect to the sole, and a pivot on which said plate can swing to permit movement of one feeler relatively to the other when the other is arrested by engagement with the sole.
74. In a sole laying machine, the combination 80 of a sole laying pad upon which an unattached sole is placed by the operator, sole holding means movable over the pad from both ends thereof to hold both ends of the sole against movement in the plane of the sole, an adjustable stop for limiting movement of the sole holding means over one end of the pad, and means operating after engagement of the stop for operating the sole holding means.
75. In a sole laying machine, the combination 85 of a sole laying pad upon which an unattached sole is placed by the operator, sole holding means movable over the pad from both ends thereof to hold both ends of the sole against movement in the plane of the sole, and means for limiting movement of the sole holding means over one 90 end of the pad comprising a block pivoted eccentrically so that the block may be turned to arrest movement of the sole locating means at different selected points longitudinally of the pad, the arresting of movement of the sole holding means 95 over the pad by the block then causing movement of the holding means to engage the sole.
76. In a machine for use in the manufacture 100 of shoes, the combination of a pad upon which an unattached sole is placed by the operator, sole holding means at an end of the pad initially withdrawn from the pad lengthwise thereof, means for moving said holding means over the pad, for permitting it to drop into engagement with the pad and for causing said holding means to find 105 the sole in the position in which it is placed by the operator to hold the sole against transverse movement, and means for lifting said holding means from contact with the pad and removing it lengthwise of the pad away from the sole.
77. In a machine for use in the manufacture 110 of shoes, the combination of a pad, means for holding a shoe on the pad, means for applying preliminary pressure thereto, members movable into and out of position over the pad to locate 115 a shoe and its sole relatively to each other, means for applying final pressure to the shoe sole, means operated by said pressure applying means for withdrawing said locating members out of contact with the shoe, and means for causing the 120 final pressure to be applied gradually.
78. In a machine for use in the manufacture 125 of shoes, the combination of a pad, sole holding and shoe locating members movable into and out of position over the pad, means for moving 130 said members over the pad to engage a sole and to locate a shoe with respect to the sole, means for applying preliminary pressure to the shoe to press it upon the pad, means for applying final pressure to the pad to force it against the shoe,

- and means operating as an incident to the application of said final pressure for withdrawing the sole holding and shoe locating members out of engagement with the shoe so that they will not interfere with the application of the final pressure, the resistance of said sole holding and shoe locating members to withdrawal from the pad being utilized to prevent a too sudden application of the final pressure.
10. 79. In a machine for cement-attaching soles to shoes, the combination of a hollow vessel, confining means for the vessel constructed and arranged to expose one portion thereof for the reception of a shoe sole, a fluid in said vessel, and means for distorting another portion of the vessel to cause its exposed portion to be distorted outwardly.
80. In a machine for cement-attaching soles to shoes, the combination of a hollow vessel of dilatable material filled with liquid, confining means for said vessel constructed and arranged to expose a portion of the wall thereof to permit it to be dilated, and means for distorting another portion of the wall of the vessel to effect dilation of the exposed wall.
81. In a machine for cement-attaching soles to shoes, the combination of a hollow vessel of dilatable material and filled with water, confining means for said vessel constructed and arranged to leave a portion of one wall exposed over an area sufficient for the reception of a shoe sole, and means for distorting another wall of the vessel to cause dilation of the exposed wall.
82. In a machine for cement-attaching soles to shoes, the combination of a hollow vessel, confining means for the vessel constructed and arranged to expose a portion of the upper wall of the vessel for the reception of a shoe sole, a fluid in said vessel, and means for distorting the bottom wall of the vessel to cause its upper wall to be dilated by pressure transmitted by the fluid.
83. In a machine for cement-attaching soles to shoes, the combination of a hollow vessel of dilatable material filled with water, confining means for said vessel constructed and arranged to expose one wall thereof to permit it to be dilated, and means for distorting the opposite wall of the vessel to effect dilation of the exposed wall by pressure transmitted by the liquid.
84. In a machine for cement-attaching soles to shoes, the combination of a hollow vessel, confining means for the vessel constructed and arranged to expose one portion thereof for the reception of a shoe sole, a fluid in said vessel, means for holding a shoe and sole upon the exposed portion of said vessel, and means for distorting the vessel to cause its exposed portion to press the sole forcibly against the shoe bottom.
85. In a machine for cement-attaching soles to shoes, the combination of a hollow vessel of distortable material filled with liquid, confining means for said vessel constructed and arranged to expose one wall thereof to permit it to be distorted outwardly, means for pressing a shoe and sole against the exposed wall of the vessel, and means for distorting another wall of the vessel to effect outward distortion of the exposed wall to cause the sole to be pressed against the shoe bottom.
86. In a machine for cement-attaching soles to shoes, the combination of a hollow vessel of distortable material filled with liquid, confining means for said vessel constructed and arranged to leave a portion of its wall exposed over an area sufficient for the reception of a shoe sole, means for pressing the shoe, including its sole, against the exposed wall of the vessel, and means for deflecting another portion of the wall of the vessel to cause distortion of the exposed wall outwardly whereby the sole is pressed against the shoe bottom.
87. In a machine for cement-attaching soles to shoes, the combination of a hollow vessel, confining means for the vessel constructed and arranged to expose a portion of the upper wall of the vessel for the reception of a shoe sole, a fluid in said vessel, means for distorting the bottom of the vessel to cause its upper wall to be dilated, and means on the confining means for locking the distorting means in distorting position.
88. In a machine for cement-attaching soles to shoes, the combination of a hollow vessel of dilatable material and filled with liquid, confining means for said vessel constructed and arranged to expose one wall thereof to permit it to be dilated, means for holding a shoe against said wall, means for distorting the opposite wall of the vessel to press the exposed wall forcibly against the sole of the shoe, and means comprising a wedge for locking the distorting means in distorting position.
89. In a machine for cement-attaching soles to shoes, the combination of a hollow vessel of dilatable material and filled with liquid, confining means for said vessel constructed and arranged to expose a portion of the wall thereof to permit it to be dilated, and a plunger operable to distort another portion of the wall of the vessel to effect dilation of the exposed wall.
90. In a machine for cement-attaching soles to shoes, the combination of a hollow vessel of dilatable material and filled with liquid, confining means for said vessel constructed and arranged to expose a portion of the wall thereof to permit it to be dilated, and a plunger operable to distort another portion of the wall of the vessel to effect dilation of the exposed wall.
91. In a machine for cement-attaching soles to shoes, the combination of a hollow vessel of dilatable material and filled with liquid, confining means for said vessel constructed and arranged to expose one wall thereof to permit it to be dilated, means for holding a shoe and sole against the exposed portion of the vessel, means for distorting another wall of the vessel to effect dilation of the exposed portion to cause the sole to be pressed against the shoe bottom, and means carried by the confining means for holding the vessel in distorted condition to permit transportation of the vessel, the vessel confining means and the shoe as a unit.
92. In a machine for cement-attaching soles to shoes, the combination of a hollow vessel of dilatable material and filled with water, a box confining said vessel constructed and arranged to leave a portion of one wall of the vessel exposed over an area sufficient for the reception of a shoe sole, a displaceable member in the bottom of the box, means for pressing a shoe including its sole against the exposed wall of the vessel, means acting on said displaceable member to deflect the bottom wall of the vessel to cause dilation of the exposed wall whereby the sole is pressed against the shoe bottom, and means on the box for locking the displaced portion in displaced position.

- so that the box, the hollow vessel and the shoe can be removed from the machine as a unit with the shoe under pressure.
93. A pad for use in pressing soles upon shoes comprising a rubber vessel, means for confining said vessel constructed and arranged to expose a portion of the wall of the vessel for the reception of a shoe sole, and a liquid filling said vessel to an extent insufficient to distend the vessel, said exposed wall being readily deformable by application of pressure and having the portion thereof which is to receive the shank portion of the sole formed with a doubly convex curvature which form it assumes when unstressed.
94. A pad for use in pressing soles upon shoes comprising a rubber vessel, means for confining said vessel constructed and arranged to expose a portion of the wall of the vessel for the reception of a shoe sole, and a liquid filling said vessel to an extent insufficient to distend the vessel and thereby rendering the exposed wall flabby, the portion of said exposed wall which is to receive the shank portion of the sole when unstressed being doubly convex so that pressure of the sole upon said portion will cause the portion thereof under the sole to become transversely concave and the portions at each side of the shank to become transversely convex.
95. A pad for use in pressing soles upon shoes comprising a rubber vessel, means for confining said vessel constructed and arranged to expose a portion of the wall of the vessel for the reception of a shoe sole, and a liquid filling said vessel to an extent insufficient to distend the vessel and thereby rendering the exposed wall flabby, said exposed wall when unstressed having the portion which is to receive the shank portion of the sole convex longitudinally and transversely of the sole so that pressure of the sole upon said portion will cause the portion thereof under the sole to become transversely concave and the portions at each side of the shank to become transversely convex, pressure of the shoe upon said sole causing the shank portion of said vessel to bulge upwardly at the two sides of the shank portion of the sole and to wrap the sole about the convex shank portion of the shoe.
96. In a machine for cement-attaching soles to shoes, the combination of a box, a flexible vessel filling said box and having a flabby wall exposed to receive a shoe sole, means for dilating the exposed wall to apply pressure to the sole, and means arranged for adjustment over opposite end portions of the surface of said wall to vary the exposed area and to control dilation of said wall.
97. In a machine for cement-attaching soles to shoes, the combination of a box, a flexible vessel filling said box and having one wall exposed to receive a shoe sole, means for dilating the exposed wall to apply pressure to the sole, and a plate arranged at each end of the box for adjustment lengthwise of the box over the surface of said wall to vary the exposed area of the wall and to control dilation of the wall.
98. In a machine for cement-attaching soles to shoes, the combination of a hollow vessel containing a fluid, confining means for the vessel constructed and arranged to expose a portion of the wall thereof for the reception of a shoe sole, means for applying preliminary pressure to a shoe and a sole positioned on the exposed portion of the wall of the vessel, and means for distorting another portion of the wall of the vessel to cause its exposed portion to apply final pressure to the sole.
99. In a machine for cement-attaching soles to shoes, the combination of a hollow vessel of dilatable material filled with liquid, confining means for said vessel constructed and arranged to expose a portion of the wall thereof to permit it to be dilated, means for preliminarily pressing a sole and a shoe against the exposed wall of the vessel, and means for distorting another portion of the wall of the vessel thereby to effect dilation of the exposed wall by pressure transmitted by the liquid and thus to apply final pressure to the sole.
100. In a machine for cement-attaching soles to shoes the combination of a hollow vessel having a flabby wall and containing a liquid, confining means for the vessel constructed and arranged to expose a portion of the flabby wall of the vessel for the reception of a shoe sole, means for preliminarily pressing a sole and a shoe against the exposed portion of the vessel, means for distorting another portion of the wall of the vessel to cause the exposed portion of the wall to be distorted outwardly and thereby to apply final pressure to the sole, and means carried by the confining means for holding the distorting means in distorting position.
101. In a machine for cement-attaching soles to shoes the combination of a hollow vessel containing a liquid, confining means for the vessel constructed and arranged to expose a portion of the wall of the vessel for the reception of a shoe sole, means for preliminarily pressing a sole and a shoe against the exposed portion of the wall of the vessel, means for distorting another portion of the wall of the vessel to cause the exposed portion of the wall to be dilated and thereby to apply final pressure to the sole, and means carried by the confining means for holding the distorting means in distorting position.
102. A device for pressing soles upon shoes comprising a box, a flexible vessel filling said box and having a surface exposed to receive a shoe sole, yokes pivoted at their ends to the sides of the box and arranged to swing lengthwise of the box, one yoke carrying a plunger to engage the toe portion of the shoe and the other yoke carrying a plunger to engage the top of the last, and means on the yokes for locking the plungers in depressed position.
103. In a machine for use in the manufacture of shoes, the combination of a box, a yielding pad filling said box and having a surface exposed to receive a shoe sole and a shoe placed thereon, yoke members having their ends hinged to the sides of the box and extending over the toe and heel ends of a last and shoe located on said surface, a plunger carried by each yoke, means for holding each plunger depressed, and means for depressing the plungers to engage the shoe and last and force it against the sole on said surface, said box and attached yokes with the shoe under pressure being transportable as a unit.
104. In a machine for use in the manufacture of shoes, the combination of a box, a yielding pad filling said box and having a surface exposed to receive a shoe sole and a shoe placed thereon, yokes pivoted at their ends to the sides of the box and arranged to swing lengthwise of the box, one yoke carrying a plunger to engage the toe portion of a shoe and the other yoke carrying a plunger to engage the top of the last, and means for depressing the plungers to press the shoe and sole against the pad.
105. In a machine for use in the manufacture of shoes, the combination of a box, a yielding

pad filling said box and having a surface exposed to receive a shoe sole and a shoe placed thereon, yokes pivoted at their ends at the sides of the box and arranged to swing lengthwise of the box, one yoke carrying a plunger to engage the toe portion of the shoe and the other yoke carrying a plunger to engage the top of the last, and means for depressing the plungers to press the sole and shoe against the pad, said means being constructed and arranged for repeated operation to increase the pressure.

106. In a machine for use in the manufacture of shoes, the combination of a box, a flexible vessel filling said box and having a surface exposed to receive a shoe sole, yokes pivoted at their ends to the sides of the box and arranged to swing lengthwise of the box, a plunger on each of said yokes, brackets arranged to be swung into position over said plungers, means 15 on the brackets for depressing the plungers, and means on the yokes for locking the plungers in depressed position.

107. In a machine for use in the manufacture of shoes, the combination of a pad, means for holding a shoe on the pad, means for applying preliminary pressure thereto, members movable into and out of position over the pad to locate a shoe and its sole relatively to each other, means for applying final pressure to the shoe 30 sole, and means operated by said final pressure applying means for withdrawing said locating members out of contact with the shoe.

108. In a machine for use in the manufacture of shoes, the combination of a pad, sole holding 35 and shoe locating members movable into and out of position over the pad, means for moving said members over the pad to engage a sole and to locate a shoe with respect to the sole, means for applying preliminary pressure to the shoe 40 to press it upon the pad, means for applying final pressure to the pad to force it against the shoe, and means operating as an incident to the application of said final pressure for withdrawing the sole holding and shoe locating members out of engagement with the shoe so that they will not interfere with the application of the final pressure.

109. In a machine for use in the manufacture of shoes, the combination of a pad upon which 50 a sole is placed in a position selected by the operator, feelers to engage the periphery of the sole so placed, levers on which the feelers are mounted, a plate having inclined slots acting on said levers to close the feelers against the sole 55 and lock them against outward movement with respect to the sole, a pivot on which said plate can swing to permit shifting of the feelers upon the pad to enable them to find the sole, means for moving said levers and plate into and out 60 of operative position to present the feelers upon the pad and to withdraw them therefrom, and means for restoring the levers and plate to normal central position operated automatically by the withdrawal of said levers and plate from 65 operative position.

110. In a machine for use in the manufacture of shoes, the combination of a yielding pad to receive a sole and a shoe on its last, last depressing means comprising brackets movable from 70 inclined positions to positions over the ends of the shoe, sleeves on said brackets movable toward the shoe, pawls for holding said sleeves in depressed position, plungers in said sleeves, levers for operating the plungers to apply pressure to the shoe, and means operated by swinging move-

ment of the plungers to their inclined position for releasing said pawls.

111. In a machine for use in the manufacture of shoes, the combination of a yielding pad to receive a sole and a shoe on its last, last depressing means comprising brackets movable from inclined positions to positions over the ends of the shoe and constructed and arranged to be returned by gravity to their inclined positions, sleeves on said brackets movable toward the shoe, pawls for holding said sleeves in depressed position, plungers in the sleeves, levers for operating the plungers to apply pressure to the shoe, and means operated by swinging movement of the plungers to their inclined positions for releasing said pawls.

112. A pad comprising a member of dilatable material to receive the sole of a shoe, and means comprising a spring metal plate incorporated in a portion of said member which is to receive the forepart of the shoe to control dilation of that portion while permitting dilation of another portion, said plate having slits extending in directions from side to side of the sole in the interior portion of the plate but not to its edge so that 90 the strips of metal formed by the slits are integral with the margin of the plate.

113. A pad comprising a member of dilatable material to receive the sole of a shoe, and means comprising a spring metal plate incorporated in 105 a portion of said member which is to receive the forepart of the sole to control dilation of that portion while permitting free dilation of another portion, said plate having slits extending in directions radially of the toe and said slits being 110 formed in the interior portion of the plate and not extending to its edge.

114. In a cement sole attaching machine, the combination of a fluid container having a sole receiving wall conformable to the shape of a shoe 115 bottom, a body of fluid of constant volume in said container, means for forcing a shoe against said wall with initial pressure to cause the wall to conform to the shoe bottom, and means for thereafter effecting upward pressure of the fluid 120 against said wall to apply final pressure to the shoe bottom.

115. In a cement sole attaching machine, the combination of a flexible fluid container having an exposed flabby wall adapted to conform to the 125 shape of a shoe bottom, means for forcing the shoe against said wall to cause the wall to conform to the shoe bottom, and means for deflecting another wall of the container to cause fluid pressure to be applied against the inner face of 130 said exposed wall to force it against the sole with sole attaching pressure.

116. A cement sole attaching machine having, in combination, a hollow rubber vessel containing a constant volume of liquid and having a sole receiving wall, a support for holding a shoe upon said wall, a plate over said wall normally in contact therewith and having an opening therein exposing the wall over an area having substantially the shape of a shoe sole but larger in size than the shoe sole, means for depressing the shoe support to sink the shoe upon the wall to cause it to be forced down away from the plate about the periphery of the shoe, and means for effecting pressure upon another wall of said vessel to cause the sole receiving wall to be forced again against the plate and into the space between the shoe and the edge of the opening in the plate.

117. In a cement sole attaching machine, the combination of a rubber container having a sole

- receiving wall conformable to the shape of a shoe bottom, a body of fluid of constant volume in said container, means for forcing a shoe against said wall with initial pressure to cause the wall to conform to the shoe bottom, and means for thereafter effecting upward pressure of the fluid against said wall to apply final pressure to the shoe bottom. 80
118. In a cement sole attaching machine, the combination of a fluid container comprising a rubber bag having an exposed flabby wall adapted to conform to the shape of a shoe bottom, means for forcing the shoe against said wall to cause the wall to conform to the shoe bottom, and means for effecting fluid pressure against said wall to force it against the sole with sole attaching pressure. 85
119. In a machine for use in the manufacture of shoes, the combination of a pad upon which a sole is to be placed in any one of a number of positions as selected by the operator, feelers constructed and arranged to engage the edge of the sole at a plurality of points on each side of the sole, means to lock said feelers against outward movement away from the sole, and a plurality of shoe positioning members one carried by each of the feelers, said members being formed and arranged to position a shoe relatively to the sole. 90
120. In a machine for use in the manufacture of shoes, the combination of a pad to receive an unattached sole, members movable over the pad and constructed and arranged to engage the sole at a plurality of points on each side of its forepart, other means for holding the heel end of the sole, and shoe engaging members carried by said sole engaging members for engaging corresponding points on the shoe to locate the shoe relatively to the sole. 95
121. In a machine for use in the manufacture of shoes, the combination of a pad to receive an unattached sole, feeler members movable over the pad to engage the forepart of the sole at a plurality of points on each side of the sole, means for locating the rear end of the sole and the shoe relatively to each other, and shoe engaging members superimposed upon said feeler members for engaging corresponding points on the shoe to locate the forepart of the shoe relatively to the sole, each of said sole engaging members and its corresponding feeler member being relatively ad- 100
- justable to effect the desired relative location of the shoe and sole at different points about the periphery of the shoe. 105
122. In a machine for use in the manufacture of shoes, the combination of a pad to receive an unattached sole, feelers acting irrespectively of the location of the sole on the pad to find the sole by engagement with its edge face at salient points on its periphery including points in the vicinity of the ends of the tip line and the ends of the ball line, said feelers acting to hold the sole in the position in which it was found, and gage members superimposed upon the feelers for engaging corresponding points on a shoe placed upon the sole to locate the shoe relatively to the sole. 110
123. In a machine for use in the manufacture of shoes, the combination of a pad, means for holding a shoe on the pad, means for effecting relative movement of the shoe holding means and the pad to apply pressure to the shoe and sole, members movable over the pad to locate the shoe and sole relatively to each other, and means operating during the application of pressure for withdrawing said locating members out of contact with the shoe. 115
124. In a machine for use in the manufacture of shoes, the combination of a pad, means for holding a shoe on the pad, means for effecting relative movement of the shoe holding means and the pad to apply pressure to the shoe and sole, members movable over the pad to locate the shoe and sole relatively to each other, and means operating after the application of some pressure and before the pressure has reached the maximum for withdrawing said locating members 120 out of contact with the shoe. 120
125. In a machine for use in the manufacture of shoes, the combination of a pad, means for holding a shoe on the pad, means for effecting relative movement of the shoe holding means and the pad to apply first a preliminary pressure and then a final pressure to the shoe and sole, members movable over the pad to locate the shoe and sole relatively to each other, and means operating between the application of the preliminary pressure and the application of the final pressure for withdrawing said locating members out of contact with the shoe. 125
